UNITED STATES PATENT OFFICE.

MORRIS P. HOLMES, OF CLAREMONT, NEW HAMPSHIRE, ASSIGNOR, BY MESNE ASSIGNMENTS, TO THE JEFFREY MANUFACTURING COMPANY, OF COLUMBUS, OHIO, A CORPORATION OF OHIO.

MINING MACHINE.

Application filed November 10, 1916, Serial No. 130,579. Renewed April 21, 1922. Serial No. 555,916.

To all whom it may concern:

Be it known that I, MORRIS P. HOLMES, a citizen of the United States, residing at Claremont, in the county of Sullivan and State of New Hampshire, have invented certain new and useful Improvements in Mining Machines, of which the following is a full, clear, and exact specification.

My invention relates to mining machines. It has for its object to provide an improved mining machine of increased flexibility whereby the same may be adapted to varied conditions with great facility. More specifically, my invention has for a further object to provide an improved mining machine whereby, without reversal of the motor thereon, either the cutting mechanism or the feeding mechanism, or both, may be reversed when desired, and whereby the machine may be made to cut in either direction. A more specific object of my invention is to provide an improved machine especially adapted to use in mines where pressure fluid only is obtainable, and to produce a machine especially adapted to longwall use, although the same is not limited thereto, and the construction described herein may be embodied in other machines than pressure fluid operated machines and in other types of machines, such, for example, as the room and pillar machine, if desired. These and other objects of my invention will, however, hereinafter more fully appear.

In the accompanying drawings, I have, for purposes of illustration, shown one embodiment which my invention may assume in practice, illustrating the same as applied to a pressure fluid operated machine of the longwall type.

40 In these drawings,—

Fig. 1 is a side elevation of the illustrative machine.

Fig. 2 is a longitudinal section view of the machine taken on line 2—2 of Fig. 3.

45 Fig. 3 is a plan view thereof with certain of the portions of the casing and of other parts broken away or removed to facilitate illustration.

Fig. 4 is a longitudinal enlarged sectional view on line 4—4 of Fig. 3, looking in the direction of the arrows.

Fig. 5 is a similar transverse sectional view on line 5—5 of Fig. 4.

Fig. 6 is a similar enlarged transverse sectional view on line 6—6 of Fig. 3. 55

Fig. 7 is a similar enlarged transverse sectional view on line 7—7 of Fig. 3.

Fig. 8 is a similar enlarged transverse sectional view on line 8—8 of Fig. 3.

Fig. 9 is a similar transverse sectional view on line 9—9 of Fig. 10.

Fig. 10 is a similar enlarged horizontal sectional view on line 10—10 of Fig. 1.

Fig. 10^a is a side elevation of the air relief mechanism detached. 65

Fig. 10^b is a vertical longitudinal section of the relief valve.

Fig. 10^c is a similar section of the relief valve with the valve at the inner end of the duct. 70

Fig. 11 is a similar transverse sectional view taken on line 11—11 of Fig. 10.

Fig. 12 is a similar enlarged transverse sectional view taken on line 12—12 of Fig. 3.

Fig. 13 is a similar horizontal sectional view taken on line 13—13 of Fig. 12. 75

Fig. 14 is an enlarged sectional view similar to that shown in Fig. 3, showing one of the bearings at the front end of the rotor shafts. 80

Fig. 15 is a detail sectional view, looking in the direction of the arrow, taken on line 15—15 of Fig. 10.

Fig. 16 is a diagrammatic view showing the machine cutting across the face in one direction.

Fig. 17 is a diagrammatic view showing the machine cutting across the face in the opposite direction.

Fig. 18 is a simplified diagrammatic view showing one connection for sumping the bar under a face preparatory to a cut along the face. 90

Fig. 19 is a similar view showing the connections for sumping and cutting along an oppositely disposed face. 95

Fig. 20 is a similar view showing the machine cutting a straight rib and making a transverse cut with one setting of the jacks, the bar herein being adjustable during the 100 operation.

Fig. 21 is a similar view similar to Fig. 20

but showing the machine making the cuts with the bar maintained rigidly connected thereto.

In the illustrative construction shown, the machine is suitably enclosed and preferably mounted to slide on its bottom over the mine bottom and having its bottom so constructed as to permit it to slide freely. Herein, the machine is shown to carry also a single thin bed plate or shoe 1 extending beneath the whole body portion of the machine and adapted to slide over the mine bottom. Between the ends of this shoe 1 is carried a suitable motor adapted to rotate in one direction and to drive the cutting and feeding mechanism hereinafter described. As shown herein, this motor is of the fluid pressure type and, while other intermeshing rotors may obviously be used, of the construction described and claimed in my copending divisional application Ser. No. 660,803, filed Sept. 4, 1923, the same being enclosed in a suitable frame section and motor casing 2, bolted or otherwise suitably secured to the shoe 1, and to the adjacent ends of end frame sections respectively carrying cutting and feeding mechanisms and hereinafter described, and having suitable parallel longitudinally disposed intersecting bores 3 therein, adapted to house the lower portion of a pair of parallel rotors 4. As shown, Figs. 2, 3 and 8 these rotors are each provided with intersecting series of spiral or helical teeth 5 and are adapted to mesh one with the other, substantially along the center line of the machine, and these rotors are provided with shafts 6 mounted in bearings in the motor casing 2.

In a preferred form, one end, and preferably the rear end, of each shaft 6, extends into a removable bearing carrying head member 8 Fig. 3 suitably attached to the motor casing and protruding into a bored out end 9 of the rotor, the end of the shaft being reduced, as shown at 10, and surrounded by a suitable oil trapping passage 11. As shown, the shaft is also provided with a further reduced portion 12 around which is disposed a ball bearing 13 clamped in position by locking nuts 14 carried on a threaded extension 15 on the shaft. The opposite end of each of the shafts, and preferably the front end thereof, is also similarly reduced, as at 16, and protruded into a suitable bearing carrying head member 17 similar to the head member 8 but preferably formed integral with the rear head of the motor casing. The rear end of the shaft is also provided with a second reduced portion 18 Fig. 14 around which is disposed a ball bearing 19, similar in construction and function to the bearing 13. In this instance, however, the head 17 is provided with a threaded portion 20 of slightly greater diameter than the bore

therein adapted to receive the ball bearing 19, and in this threaded portion is carried a thrust adjusting member 21 having an inwardly disposed flange 22 at its front end. Against this flange, in turn, rests a ball thrust bearing member 23 of the ball and split ring type having its inner edge extending between a plurality of split rings 24, grooved on their adjacent faces to receive it, and clamped on a further reduced portion 25 on the shaft 6. As shown, these rings 24 and a ring 26 between the same and the bearing 19, are suitably locked in position by a lock nut 27 carried on a still further reduced and threaded portion 28 on the shaft 6, a cooperating ring 29, threaded onto the inner surface of the member 21, being disposed around the same and cooperating with the several parts just described to hold the same in position. Obviously, through this construction not only will the rotor shafts be provided with suitable journal bearings, but the thrust of the shafts will be absorbed, and any suitable adjustment of the bearing members to take up the thrust which may be desired, may be readily obtained through the adjustment of the member 21, as, for instance, by inserting a suitable tool in notches 30 therein, the member 21 then being locked in position by any suitable means. Attention is here also directed to the fact that this construction, wherein the bearings are extended into or housed in the ends of the rotors, results in a very compact construction longitudinally, a feature of distinct importance as it enables the length of the machine and the resultant handling room to be maintained at a minimum while retaining a motor of maximum size.

In the form of my invention shown, the air, steam, or other pressure fluid for imparting rotation to the rotors 4, is supplied thereto from a longitudinally disposed passage 31, Figs. 2 and 8 in turn having supply connections at the cutter carrying end of the machine hereinafter described, and located in the bottom of the motor casing and communicating with the rotors 4 through an upstanding inlet 32. This inlet delivers the pressure fluid at a point below the mesh line of the rotor teeth and substantially at the point of intersection of the sets of teeth on each rotor, so that, as is usual in such motors, the expansive effect of the pressure fluid results in the rotation of the rotors in opposite directions, the pressure fluid expanding as the rotors are revolved, and thereby tending to impart torque to the rotor shafts, while the exhaust fluid passes out from the rotors at the top of the same, and into a chamber 32^a formed between cover plates 33 and the top of the rotor casing 2. As shown, this exhaust is herein allowed to pass

out of the chamber 32^a through outlets 34 and 35, Fig. 8 in the top of the motor casing of which the outlets 34 are disposed in the center line of the rotor casing, while the outlets 35 are disposed at the sides of the rotor casing. Herein the center outlets are also in the form of a plurality of side outlets disposed one against the other. As illustrated, these outlets are provided with apertures 36 communicating directly with the chamber 32^a and with downwardly and upwardly disposed passages 37 extending down beneath baffle plates 38, and upward and outward to the atmosphere. Thus, it will be noted that the exhaust from the rotors is caused to pass out of the same in such a manner as not only to direct it away from the mine bottom or other adjacent mine surfaces, thereby avoiding the creation of dust, but also to carry out any dust or coal particles which would otherwise be drawn into the motor, the same thereby being used to protect the motor against such wear of its parts as would normally result from the ingress of these gritty particles.

The pressure fluid for rotating the rotors 4 is herein also conveyed to the chamber 31 from a suitable annular chamber 39, Fig. 4 preferably formed in a supplemental rear head 40 attached to the front end of the rotor casing by suitable bolts 41 and removable with the rotor casing if desired. As shown, these bolts and the supplemental head may also preferably serve as a means to clamp the head 8 in position. As shown, the annular pressure fluid passage 39, above described, in turn is provided with a suitable pressure fluid inlet 42 which is in turn controlled by a suitable intake valve mechanism, which controls the pressure fluid supply from a chamber 43 provided in a rear frame section or casting 44, disposed at the rear end of the machine, and suitably bolted to the motor frame section, herein through the head 40, by suitable bolt connections above the bottom of said sections. To this chamber 43 is connectable at one of a plurality of points as hereinafter described, an air or other hose line 45 through suitable connections 46, the latter preferably including a screen 47 so disposed as to prevent the entry of objectional particles into the mechanism.

In the form of my invention shown herein, the intake valve mechanism comprises a tubular section 48 threaded at 49 into the casting 44 in which the chamber 43 is formed, and a cooperating inter-threaded section 50 extending through a front vertical wall 51 of a bed casting 52 and the rear wall of the supplemental head 40, a suitable packing 53 surrounding the member 50. As illustrated, this member 50 is provided with a suitable valve seat 54 upon which is seated a valve member 55 having a

stem 56 movable in a suitable sleeve 57 formed integral with the member 50 and normally held on its seat by the pressure of the pressure fluid acting on one side of the valve member and the cooperation of a coiled spring 58 disposed between the sleeve 57 and a member 59 threaded on the end of the valve stem. Obviously, by movement of this member 59 the valve 55 may be opened whenever desired to permit pressure fluid to pass from the line 45 to the chamber 39 and the motor, the spring 58 and the fluid pressure of the line acting at all other times to hold the valve securely upon its seat.

In my improved construction, the member 59 is also connected through a threaded connection 60 with a longitudinally disposed rod 61 extending through the motor casing 2 to the front end of the machine, and suitably connected at 62, as by pivoting, to a bell crank lever 63 pivoted at 64 on a suitable bracket 65 on the frame, and provided at its opposite end with a cam or knob-like portion 66 adapted to engage a wedge member 67. As shown, this wedge member is adapted to slide over a suitable bed or surface 68 formed on the bracket 65, and is provided with a rearwardly extending shank 69 slidable in suitable bearings and having a rack 70 on its front end meshing with a suitable pinion 71. This pinion is in turn suitably journaled and provided with a shaft 72 fixed to an operating lever or handle 73 preferably carried on the top of the frame and at the front end thereof. It will also be noted that this handle 73 is provided with a suitable spring pressed plunger 74 adapted to engage in suitable corresponding notches 75 formed in the top of the frame, and thereby hold the lever 73 in any desired position of adjustment. Obviously, through the construction just described, when the lever 73 is adjusted, the wedge 67 will be reciprocated in such a manner as to operate the bell crank 63 and therefore enable the valve 55, located at the rear of the machine, to be operated readily and conveniently by an operator disposed at the front end of the machine.

In this connection, it should also be noted that, as shown in Fig. 10, I have provided improved means for supplying lubricant to the pressure fluid actuating the rotors. This lubricant is carried in a suitable reservoir or chamber 76 disposed concentrically with the upper end of the shaft 111 and preferably formed in the casting 44. As shown, lubricant is supplied to this reservoir through openings in the top thereof, normally closed by removable plugs 77, suitable screens 78 being provided in the openings to prevent the entry of dirt or the like. In the construction shown in Figs. 10 and 11, it will be noted that I have provided a valve member 79 controlling the flow of the liquid

in the chamber 76, this valve member being provided with one or more upper ducts 80 and one or more lower ducts 81, and being journaled, as at 82, in the casting in which 5 the reservoir is formed, and provided at its upper end with a reduced portion 83, to which is rigidly attached a handle 84. It will also be noted that these ducts 80 and 81 are disposed on opposite sides of a baffle 10 plate 85 extending into the reservoir, and that the two ducts communicate with the air chamber 43 by means of communicating ducts 86 and 87. Thus, it will be noted that the air passing through the chamber 43 will 15 be allowed to enter the top of the oil reservoir 76, and through its action upon the surface of the lubricant therein, thereby neutralize the effect of its pressure and cause the lubricant to flow by gravity through the 20 lower orifice in drops adapted to commingle with the incoming pressure fluid. Obviously, the lubricant will thus be distributed properly to all the working parts of the motor. Through turning the lever 84, 25 this supply of lubricant may, of course, be regulated as desired.

Herein, attention is also directed to the fact that improved means are provided for eliminating the bodily downward movement 30 of the rotors into contact with the casing which results in sparking and for reducing the wear on the motor bearings, both of which result when the pressure fluid supply for the motor is cut off. These means 35 are made necessary by the fact that when the pressure fluid supply is arrested, the continued rotation of the rotors causes a vacuum to be formed in the motor casing, which results in a cramping down effect of the motor shafts upon their bearings, and dangerous 40 sparking between the rotors and the motor casing as well as destructive wear of those bearings.

To overcome this difficulty I provide a relief mechanism which may be of any well-known and suitable form, to permit the entry of air at atmospheric pressure to the chamber 39 and to the motor, when the pressure therein is reduced below atmospheric 45 pressure, as a result of the continued rotation of the rotors after the supply of pressure fluid has been cut off.

In the drawings there is shown one form 50 of relief mechanism. It is indicated, as an entirely, at 88. It comprises an air duct or tube supported in the wall of the chamber 39. It has a valve and valve seat as at 88^a, normally held by springs 88^b, which yields, however, when pressure outward falls below 55 that of the atmosphere and permits the valve to move inward and allow the entrance of air, thereby preventing the forming of a vacuum in the rotor chamber and obviating the difficulties heretofore experienced 60 with rotor bearings. The valve and its seat at their adjacent ends, each meshing with

may be normally positioned as in Figure 10^b, or at the inner end of the air duct, as shown at 88^c in Figure 10^c.

This is an important feature as it is found to be impossible for such a motor to be used 70 in a mining machine in an efficient form without such a relief device, it being impossible on the one hand to permit sparking in many mines due to the presence of gas and the consequent danger of explosion 75 wrecking the entire property, while, on the other hand, the only other way to eliminate the sparking is to increase the rotor clearance which requires such a tremendous increase in clearance as to be impractical from 80 the standpoint of motor efficiency. Further, even when increasing the clearance the difficulty with the abnormal wear on the bearings would be still encountered, whereas in my improved construction the sparking and 85 bearing wear are both eliminated at the same time. Attention is here also directed to the fact that this relief connection is carried upon the machine and as a separate and distinct connection from the pressure fluid supply, and that both the relief and supply connections are disposed within the lines of the machine and more particularly within the transverse, as distinguished from the longitudinal, limits of the longitudinally disposed 90 motor casing in such manner as to produce a very compact construction laterally.

The construction and operation of the motor as well as its disposition and connections necessary to make it function in a 100 mining machine and more particularly in my improved mining machine now having been established, we will next consider the means by which the rotation of its plural rotors is imparted to the cutting mechanism of the 105 machine. In my improved construction, it will be noted that means are provided whereby the cutting mechanism may be rotated in opposite directions in such manner as to 110 adapt the machine to right or left hand cutting, and that the opposite rotation of the cutter chain is effected without reversing the motor, herein through connecting it to different rotors, improved means also being provided whereby it is made-impossible for 115 an ignorant operator simultaneously to connect the cutting mechanism to both rotors. Herein, it will be noted that the front ends 120 of the shafts 6 are provided with extensions 89 protruding beyond the threaded portions 15 thereon, and that splined to each of these portions is a pinion 90 adapted to be shifted back and forth along the spline by means of a shipper ring 91 and a suitable shipper member 92 pivoted at 93 on the supplemental head 40. As shown, these shipper members 92 are also provided with suitable interlocking mechanism of any desired form, herein shown to comprise rack portions 94 125 130 and pinion portions 95 each meshing with

an intermediate pinion 95 which is carried on a stud 96 and rotatable by means of a suitable handle 97. As a result of this construction, when the handle 97 is rotated in one direction, one shipper member 92 will be thrown in one direction and the other shipper member will be thrown in the opposite direction, causing an opposite movement of the pinions 90, and throwing one of the same out of engagement with a gear 98, while the other is thrown into engagement with that gear. Thus, it will be noted that the gear 98, while driven from two constantly oppositely rotating members, may be driven in either direction at will, and that it is impossible for an operator to throw both pinions 90 into mesh with the gear 98 at the same time.

This gear 98 is, in turn, preferably provided with a rearwardly extending sleeve 99 splined to a shaft 100 which is, in turn, preferably integral with a cooperating bevel gear 101 disposed at the rear end of the sleeve 99. As shown, roller bearings 102 are provided between the sleeve 99 and a suitable removable bearing carrying member 103 located on the rear wall of the head 40, and a suitable thrust bearing 104, preferably of the ball type, is provided between the shaft 100 and the rear end of the motor casing to take the thrust of the pinion 101. In a preferred form, the front end of the shaft 100 is also preferably mounted in suitable roller bearings 105, and both these bearings 102 are disposed in removable sleeves 106 and 107 and supplied with lubricant through suitable lubricant ducts having communication with the chamber 39 through which the lubricant-laden pressure fluid passes to the motor.

Meshing with the bevel gear 101, is a cooperating bevel gear 108 connected to the cutter chain driving mechanism of the machine. As shown, this gear 108 is provided with a sleeve 109 bearing against a suitable thrust bearing 110, preferably of the ball type, surrounding the upper end of a vertically disposed stud 111 on which the gear 108 is rotatably mounted. In a preferred form, this gear 108 is also splined to a sleeve 112 preferably formed integral with a cooperating smaller pinion 113 disposed below the gear 108 and above a bearing support 114 adapted to receive the lower reduced end of the stud. As shown, the stud is also provided with a suitable inner removable bearing sleeve 115. Thus, when the bevel gear 101 is rotated, its fellow 108 will be rotated, and the pinion 113 will be rotated.

This pinion 113, in turn, meshes with a larger gear 116 suitably fixed to a forwardly located vertical shaft 117 (hereinafter described) adapted to be connected to the lower cutter chain sprocket 118, jour-

naled between the frame and the lower end of the gear 116, through a suitable clutch including a ring 119. As shown, this ring 119 is provided with suitable depending interlocking fingers 120 of well known construction, adapted to engage with cooperating notches 121 formed in the chain sprocket 118, in such a manner as to cause the latter to be connected to or disconnected from the rotating gear 116 whenever the clutch mechanism is operated. Carried upon this sprocket 118 is a cutter chain 122 of the usual construction, and mounted to turn about the lower end of the shaft 117, into any desired angular position relative to the shaft, herein including opposite lateral positions and a longitudinal position is a cutter bar 123, along and around which this cutter chain extends and is movable when the clutch is connected. Thus, obviously, by connecting or disconnecting the clutch, the movement of the cutter chain may be started or arrested, as desired, no matter what may be the angle of the cutter bar 123 with respect to the shaft 117.

In order to facilitate the operation of this clutch, the ring 119 thereof is engaged in the usual manner by a plurality of arcuate lifters 124 of well known construction, in turn pivotally connected to pivoted parallel arms 125 journaled on the frame. As shown, one of these arms 125 is pivotally connected to a reciprocable member 126 having a pull handle 127 disposed on the outside of the casting. Obviously, by pulling this handle 127 the clutch may thereby be operated to connect or disconnect the cutter chain sprocket and the motor. It will also be noted that in order to maintain the clutch controlling handle 127 in any desired position, I have provided, as shown in Fig. 15, an eccentric 128 on the handle 127. Thus, when the handle 127 has been pulled out, the operator, by rotating the eccentric 128, may lock the handle in the desired position shown in that figure. Also, by rotating the eccentric until concentric with the member 126, before pushing in the latter, and then rotating the eccentric, the handle may be locked in its position.

Attention is also directed to the fact that in order that the shaft 117 may be maintained in proper position relative to the frame, and the minimum of difficulty experienced with its bearings, the upper end of this shaft is reduced and carried in a suitable sleeve-like portion 129 formed on the upper casing 44 and enclosed by a removable sleeve 130 having a lower flange 131 disposed between the casing 44 and the upper surface of the hub of the gear 116, while the lower end of the stud is provided with a flange portion 132 adapted to engage the lower surface of the gear hub. It will also be noted that the lower end of the shaft is reduced and

seated in an upstanding bearing member 133 seated on the shoe 1, and to which the cutter bar 123 is clamped by suitable bolts 134, a removable bearing sleeve 135 being provided between the member 133 and the shaft. As shown, this sleeve 135 is also provided with a flanged upper end holding a suitable bearing ring 136 in position within the lower end of the gear 116, while a ring 137, disposed between the lower surface of that gear and the upper surface of the cutter bar 123, holds in position a flanged removable bearing sleeve 138 disposed between the gear 116 and the sprocket 118. Attention is also directed to the fact that the shaft 117 is made hollow and that a bolt 139 extends longitudinally through the same and is threaded into the shoe 1 in such a manner as to give increased rigidity, the thrust being taken by the shoe.

We will now refer to the means for operating the feeding mechanism. In my improved construction this mechanism is likewise driven from the motor and connected thereto in such manner that the machine may be moved over the mine bottom in either direction at the same or different predetermined speeds without reversing the motor. In a machine of the type herein disclosed this mechanism is also located at the opposite end of the motor from the cutting mechanism and driven from the opposite end of the motor from that driving the cutting mechanism. In the particular construction shown it is also driven through a plurality of transmission or power trains, improved provision being made for selectively connecting either train to the motor whereby the machine may be propelled at a predetermined slow or cutting speed in either direction and each train also having a connectible train whereby the machine may be propelled at a predetermined faster speed in either direction. Herein it will be noted that the rotation of the rotors 4 is conveyed to a centrally located gear 140 at the rear of the motor casing, by a transmission and reversing mechanism of the character described above in connection with the rear end of the machine, and only differing therefrom by being connected to the front ends of the rotor shafts 6. Thus, the description of this transmission reversing mechanism need not be repeated. This gear 140 is journaled in suitable bearings formed on the frame and rigidly connected with a longitudinally disposed shaft 141 of a forwardly extending pinion 142, by means of a nut and bolt connection 143. As shown, this shaft 141 is journaled at a point intermediate its ends in suitable roller bearings 142^a, and at its front end in a casting 144 carrying the bearings 142^a. This casting 144 is connected to a front frame section 144^a and is similar to the supplemental rear head 40, housing the transmission and reversing mechanism, and likewise removable with the motor casing if desired. Here it will also be noted that frame 144^a is suitably bolted at points above its bottom to the motor frame section, the machine thus comprising three frame sections including the rear frame section 44, the motor frame section including the head 40 and casting 144, and the front frame section 144^a, all of which are rigidly bolted together at points above their bottoms and slidably over the mine bottom, herein on the shoe 1. As illustrated, the bearings 142 are also supplied with lubricant from a suitable passage 145 formed in the casting and communicating with an oil cup 146. The pinion 142, in turn, meshes with a larger gear 147 rotatable on a suitable bearing 148 rigidly connected to the casting 144. A smaller bevel gear 149 is carried on an intermediate plate 150 rigidly connected to the gear 147. This pinion 149, in turn, meshes with a larger bevel gear 151 splined to the lower reduced end of a rotatable shaft 152, which is in turn carried in a suitable bearing 153 mounted on a casting 154, which is rigidly secured to the lower frame casting 144^a. Suitable passages are provided for lubricating the gears 147, 149, and 151, from any suitable source (not shown). As shown an inner removable sleeve 155 is also provided between the shaft and the bearing, and a thrust ring 156 is disposed between the gear 151 and the bearing 153 and sleeve 155. As shown, the upper end of this shaft 152 is successively reduced, and the same carries on its lower reduced portion 157 a pinion 158, preferably having formed integral therewith the outer casing of a friction clutch including a movable element 159 controlled by toggles 160 and adjustable in a well known manner by vertically moving its block 161 on the second reduced portion 162 of the shaft. As in the usual construction, a threaded nut 163 is provided on a threaded portion 164 on the upper end of the shaft, and a coiled spring 165 is provided between this nut and the block 161, so that the friction may be regulated as desired and set at any desired point. Controlling this friction is a rocking shipper 166 pivoted at 167 and operable by rotation of an eccentric 168 when the eccentric is rotated by a bevel gear 169 thereof meshing with a beveled rack 170 formed on an adjustable elongated controlling lever or handle 171. Thus, obviously, by movement of this handle 171 in opposite directions, the friction may be applied or released within the limits prescribed by the nut 163, and the pinion 158 will thus be connected to or disconnected from the rotating shaft 152.

Cooperating with this pinion 158 and rotated thereby, are the fast and slow feed mechanisms, of which the fast feed mecha-

nism is preferably used in moving the machine about the mine although it may be used in sumping in soft cutting, while the slow feed mechanism is preferably used 5 while the machine is cutting during sumping or transverse cutting in average and hard cutting, and of which each mechanism is adapted to be driven in either direction by the motor without reversing the latter, 10 as herein above mentioned. Of these feed mechanisms, we will first describe the fast feed mechanism. It will be noted that the ear 158 meshes with a larger gear 172, carried on an adjacent upright stud 173. This 15 gear 172 is normally freely rotatable on its stud. However, when it is desired to drive the feeding mechanism at its fast speed, a ear 174 disposed above the gear 172 and provided with clutch teeth 175 meshing with 20 cooperating clutch teeth 176 on the gear 172, is lowered on the stud 173 and thereby connected with the gear 172, causing the same to rotate together. As this gear 174 normally meshes with a large feed driving gear 177, rotatable with a feed operating member, herein in the form of a sprocket 178 and carried on a stud 179 at the rear of the frame, said operating member is accordingly rotated at high speed in such a manner 25 that the flexible feeding member cooperating therewith, herein in the form of a feed chain 180 meshing with the sprocket 178, is caused to be fed rapidly through the machine in a manner hereinafter described. It 30 will also be noted that through the selective connection to the motor, herein in the form of the selective connections to the rotors thereof the flexible feeding member may when desired be drawn through the machine at the same speed in the opposite direction. Thus, it will be observed that means are provided for at will drawing in at a high predetermined speed either of the 35 two flexible feeding portions comprised in the flexible feeding mechanism, herein in the opposite ends of the chain 178, and extending from the feeding mechanism. Further, it will be noted that the feeding mechanism during each of these operations is subject to 40 friction control through the automatically releasable friction device, herein above described, so that the feed will be released if an obstruction is encountered, while through the manually operated controlling mechanism for the friction mechanism it is not only possible for the operator by slipping the friction to reduce the speed as desired below its predetermined maximum but also to load the friction to varying degrees as 45 necessary to maintain the predetermined speed.

In order to control the connection of this clutch 175, 176, the gear 174 is provided with an upper sleeve 181 having a shipper ring 182 thereon engaged by a clutch ship- 50

per 183 pivoted at 184 on a vertically adjustable pivot and movable upon movement of an eccentric 185 carried on a shaft 186. As shown, this shaft has fixed thereto a bevel gear 187 meshing with a cooperating bevel gear 188 on a short controlling lever or handle 189, the latter being movable into a plurality of positions indicated by the notches 190. It will also be noted that the pivot point of the shipper 183 may be adjusted as desired by removing the lock nuts 191 and adjusting the bolt 192 on which the pivot pins 184 are carried. The detail of this mechanism does not form a part of my present invention. Through the provision of this mechanism, it will be obvious that when the lever 189 is moved about its pivot, the clutch mechanism 175, 176 will be adjusted in such a manner as to throw in or throw out the fast feed whenever desired. 55

The slow speed mechanism is herein also connected to the pinion 158, and the rotation of this pinion is also conveyed to the feed sprocket 178 through the gear 177. However, in this instance, means have been provided whereby the speed of rotation of the feed sprocket is materially reduced and its direction reversed. These means include a gear 193 meshing with a smaller pinion 193^a preferably integral with the gear 172, 60 and carried on a supplemental stud 194. In a preferred form, a second upper pinion 195 is formed integral with this gear 193, and in turn meshes with a larger gear 196 carried on another supplemental stud 197. This stud is in turn provided with a small upper pinion 198 meshing with a large upper gear 199 carried on the upper end of the shaft 173. This gear 199 is in turn provided with clutch surfaces 200 on its lower face adapted 65 to engage with cooperating clutch surfaces 201 on the shipper ring 182. Thus, when the controlling member 189 is thrown in the opposite direction from that described in connection with the fast feed, power will be transmitted from the pinion 158 to the gear 177 through this train of gearing, and the feeding mechanism will be driven at a 70 materially reduced speed. Obviously, by changing the relative sizes of the gears 198 and 199, the speed of feed may be still further regulated, and it should be understood that I contemplate the substitution of gears of different sizes in order to obtain a wide range of feeding speeds. Thus, it will be 75 observed that means are here provided for drawing in either portion of the flexible feeding means at a predetermined cutting speed through friction mechanism set to release automatically when a predetermined load is exceeded and also manually controllable to decrease the speed of feed below its predetermined maximum as desired, by operating the manually operable controlling means to slip the friction as necessary. 80

Attention is here directed to the fact that through the fast and slow feed mechanisms and the mechanical connections thereof to the motor, heretofore described, it is thus made possible to draw in either portion of the flexible feeding member at a predetermined fast speed or at a predetermined slow speed. It will also be evident that each of these feeds is subject to a friction control, i. e. releasable on overload, and that, through the manual controlling means provided it is possible to reduce each of these predetermined speeds as desired by slipping the friction in such manner as to enable graduation of the feed within wide limits. It will also be observed that through my improved mechanism these variations in speed and direction of feed are obtainable without reversing the motor and that they are also obtainable during rotation of the cutter chain in either direction in such manner as to enable these desired results to be available whether the machine is arranged to cut from right to left or from left to right.

Cooperating with the mechanism just described, I have provided interlocking means whereby the friction may not be increased or loaded when cutting, i. e. when feeding at slow speed, as experience has shown that if the runners are permitted to increase the friction when cutting, serious damage to the machine results. This interlocking means includes the provision of a projection 202 on the lever 171, and the arrangement of the lever 189 in such a position that when it is thrown over to connect the parts for slow feed, that is, the cutting feed, the friction lever 171 will engage with the end thereof and thereby be prevented from being moved to friction loading position. Obviously, by such an arrangement, while the operator may not load the friction when cutting or move the feed controlling lever 189 to fast feed without first releasing the friction, he may, without any interference whatsoever, load the friction when the machine is being moved about the mine or fast speed. It will also be evident that the interlocking means will function in either direction of operation of the feeding mechanism.

In the operation of the longwall machine described herein, it will be understood that the feed chain 180 is passed through the guides 203 and 204 located at the opposite sides of the feed sprocket 178, in a well known manner, and that the ends of the chain are connected to supports 205 or 206 adjacent the opposite ribs, in a well known manner, the bar being swung around beneath the coal and substantially at right angles to the body portion and maintained in this position as the machine is moved across the face. This method of operation is illustrated in Fig. 16. It should be understood, however, that my improved machine

is adapted to operation in either direction through the provision of the improved means whereby, although the rotors are always rotated in one direction, the feeding mechanism and cutting mechanism may be driven in opposite directions. When the machine is fed in the opposite direction, the cutter bar 123 is reversely disposed laterally and the chain 180 is reversed as shown in Fig. 17. In the course of this operation, it will also be obvious that the supply of pressure fluid, instead of entering through the inlet 45 indicated, should enter through an inlet 207 disposed on the opposite side of the machine and communicating with the chamber 43 through a suitable communicating chamber 208, the unused inlet being normally plugged by a suitable removable plug 209. It will also be obvious that in whatever direction the machine is moving, the cutter bar 123 may be swung around its pivot by power through connecting the chain 180 with a suitable flange 210 on the cutter bar, the chain then being provided with a suitable hook, and extending around in a suitable groove 211 formed on the front head. Obviously, the movement of the cutter bar may then be limited by suitable stops 212 on the base casting 52. As shown, the bar is held in each of its laterally extending cutting positions and in its longitudinally disposed position, by means of a removable pin 213 receivable in registering holes in the front frame and the cutter, and itself locked in place by pivoted cam-like latches 214.

More specifically considering the operation, it will be noted that with the machine frame and bar disposed parallel to a face at the desired point adjacent or spaced from the rib and with the feeding end of the machine in advance of the bar, the cutter bar may be swung about its pivot and under the face at the desired speed by extending the portion of the flexible feeding member adjacent the face around the front surface of its lateral guide and rearward between the machine and the face to the member 210 on the bar, as shown in Fig. 18, and then rotating the feeding mechanism in the desired direction at the predetermined slow or cutting speed. Here it will also be evident that, if the cutting is abnormally hard, the friction may be slipped to reduce the speed to the desired fractional speed, and that, if the cutting is unusually soft the fast speed feed may be used or a suitable fractional speed thereof similarly obtained by slipping the friction. When the bar is dumped into the face and the frame and bar are disposed in the position shown for example in Fig. 16, the extremity of the flexible feeding portion is disconnected from the member 210 preferably reversely reeved relative to its lateral guide and extended in advance

of the machine and parallel to and closely adjacent the face as shown in that figure. While not preferred, the other flexible portion may be utilized in lateral feeding. In 5 either cut the selected portion is preferably disposed as illustrated in Fig. 16, i. e. in a single stationary strand having its end fixed to the anchor or jack 205, as shown. When the parts are in this position by simply 10 again rotating the feeding means in the same direction and at the slow or cutting speed, or any one of the alternative speeds above described, the machine is moved bodily along the flexible portion and the face 15 to undercut the latter. It will here be observed that when it is desired to cut in the opposite direction on the same face, the operation may be the same save that the machine is reversely disposed when arranged 20 parallel to the face, the cutter bits are reversed, the cutter chain is rotated in the opposite direction, herein by connecting it to the other rotor, the extremity of the other flexible feeding portion is successively 25 reversely disposed relative to the opposite lateral guide, and the feeding mechanism is reversed in such manner as to draw in the other portion at the speed desired, this reversal of the feeding mechanism herein being obtained without reversing the motor. 30

Attention is also directed to the fact that in my improved construction it is possible for the machine to operate similarly and in either direction when for any reason it must be disposed as shown in Figures 16 and 35 17 but cutting on the opposite side of the machine, as illustrated in Fig. 19. When cutting under such conditions it will be noted that the other flexible portion of the 40 feeding mechanism from that preferred when cutting as shown in Figs. 18 and 16 will be utilized to swing the bar in under the face and propel the machine along the face in that direction, while the other portion 45 from that used in Fig. 17 will be utilized to perform these operations when cutting in the opposite direction, the feeding mechanism in each instance being operated reversely to draw in these different portions 50 at the suitable speed or speeds mentioned and without reversing the motor. In such cutting it will also be understood that the cutter bits and cutter chain will be reversed from the relation shown in Figs. 16 and 18, 55 the reversal of the cutter chain in this instance as in the preceding instance also being accomplished without reversal of the motor. Here, as in all lateral cutting, if desired in passing from the sumping arrangement 60 to the transverse cutting arrangement, the preferred flexible portion used in swinging the bar may be re-arranged as described in connection with Fig. 18 and utilized as the anchored end during the transverse cut, 65 or if desired, the other end may be connected to a jack at the face in advance of the machine during the sumping operation and the sumping end thereafter reversely arranged as shown in Fig. 19 so that instead of acting as the working end it becomes a 70 slack end during the transverse cutting operation.

If in any of the cutting previously described or in cutting short faces it is desired to leave a straight rib, as distinguished 75 from the curved rib obtained by swinging the bar, it will also be noted that by laying the machine parallel to the rib with its cutter bar held rigidly in its longitudinal position and by extending the flexible portion then adjacent the rib, along parallel thereto between the machine and the rib to its anchor, then located near the face, as shown in Fig. 20, the machine may be 80 sumped directly longitudinally into the face to extend the rib as desired by simply operating the feeding mechanism to draw in that flexible portion either at the predetermined cutting speed, the predetermined 85 high speed, or the desired fractional speed 90 of either of the same suitable to the conditions encountered, the reaction of the coal against the cutter bits then acting to throw the rear end of the machine toward the rib 95 in such manner as to insure the machine being directed longitudinally. In practice, however, the predetermined slow or cutting speed is much preferred for all cutting operations and especially this one as by its 100 use the "jumping" of the machine which is necessarily encountered when feeding on a friction and which is so highly dangerous and destructive when the machine is in the hands of any but the most skilled operator is eliminated and a steady safe suitable speed is provided which even the most ignorant operator may use with entire safety. 105 After the bar is thus sumped under the coal, by swinging the frame around the bar pivot, as through releasing the latter and drawing in the other flexible portion fixed to an abutment disposed at the face and in advance of the machine, the latter may be prepared for 110 the transverse cut, and make this cut after the bar has been locked in its lateral position shown in Fig. 16. Here, it will be observed that it may make both of these cuts without reversing the motor or the rotation of the cutter chain. It is also important to 115 notice that it is possible in my improved construction, through the use of my improved feeding mechanism, to connect the extremities of both flexible feeding portions in one setting, one to the face adjacent the rib and the other to its jack used in transverse cutting, and then after the sumping operation is finished and the bar pivot has 120 been released, swing the machine frame 125

around into position for transverse cutting, and all by reversing the feeding mechanism and without reversing the cutting mechanism or reversing the motor. Further, it will be evident that in my improved construction such a cut may be made at either rib by reversing the cutter bits, reversing the direction of the cutter chain, utilizing the other flexible feeding portion in the sumping operation from that previously used, utilizing the other feeding portion from that previously used in the combined swinging-transverse cutting operation, and connecting the feeding mechanism and motor, first, to cause movement along the sumping portion and, second, to cause movement relative to the swinging and transverse moving portion.

In my improved construction it will also be noted that it is possible for the bar to be inserted to extend a straight rib and thereafter moved transversely with one setting of the jacks but with the bar maintained in rigid relation and with the machine more compactly disposed in certain respects. This usage of my improved construction is shown in Fig. 21 wherein it will be noted that when the bar is fixed in one of its lateral positions and the machine disposed with the end of the bar in contact with the face and the frame and bar disposed angularly relative to the latter, the flexible portion nearest the rib may be extended around the chain guide 211 on the cutter carrying end of the machine and connected to a jack adjacent the face, while the other portion is extended around its guide in the manner shown in Fig. 16, and then off to a jack at the face but at a point removed from the machine. With such an arrangement, upon drawing in the first mentioned portion at a cutting speed while the cutter chain rotates, the bar will be forced into the face in such manner as to cut a substantially straight rib as indicated and to bring the machine into position for its transverse cut, which may be made whenever this position is reached by simply reversing the feed and drawing in the other flexible portion without resetting any jack. In this transverse operation as when cutting as shown in Fig. 20, if desired the end of the flexible portion initially used to advance the bar into the face may be disconnected. Also, if in any lateral cutting it is desirable that this end be connected, as when obstacles requiring angling or reverse pulls on the frame are expected, this may be done without affecting the transverse operation, as it will thereafter be paid out as the other portion is drawn in. In making the sumping cut as in either Fig. 20 or Fig. 21, it will also be observed that whenever for any reason it is desired to move the machine frame away

from the rib this may be readily done by reversing the feed in such manner as to draw in the flexible portion extending along the face, it being possible in my improved construction to angle the machine in either direction relative to the flexible portions by alternate drawing in operations on the different portions. Attention is also directed to the fact that this summing operation may be carried out at a right hand or a left hand rib by simply adapting the flexible portions used in the different operations to the lateral position of the bar. It will also be noted that in either case, depending upon the cutting encountered, the speed of feed may be varied from its predetermined maximums as hereinabove described.

As a result of my improvement it will be observed that it is possible to operate the mining machine to draw in either of its flexible portions at the desired predetermined cutting speed, to change from drawing in one at this speed to drawing in the other at the same speed, to draw in either of said portions at a higher predetermined speed, to vary either the predetermined cutting or the predetermined high speed by slipping the friction, to have each feed include an automatically acting friction release releasable on overload, to load only the fast feed, to prevent movement from fast to slow speed or vice versa without first releasing the friction, to sump by swinging the bar laterally and cut in either direction relative to the same face or in either direction relative to an oppositely located face, to sump to produce a straight rib at a predetermined cutting speed relative to one flexible portion disposed along the rib, and to feed transversely thereafter at the same speed relative to the other portion, both sumping and transverse cuts being made with one setting of the flexible feeding portions or jacks, to make this straight ribbed sumping cut and following transverse cut with the bar rigidly connected throughout or angularly adjusted between the cuts, and to feed the machine transversely with or without the rearwardly extending flexible portion connected to its jack to permit reverse pulls on the machine, all of these operations of the feeding mechanisms being obtainable in my improved construction without the reversal of the motor, and even the cutter chain being reversible without reversal of the motor. These and other features and advantages of my improved construction will, however, be clearly apparent to those skilled in the art.

While I have, in this application, described in detail one embodiment which my invention may assume in practice, it is to be understood that the form thereof shown herein is used only for purposes of illustra-

tion, and that the invention may be modified and embodied in other forms of longwall machines applied to machines of other than the longwall type without departing from its spirit, it being my intention to include all such modifications within the scope of the appended claims.

What I claim as new and desire to secure by Letters Patent is:

10. 1. A mining machine comprising cutting mechanism including a cutter chain driving sprocket, machine feeding mechanism including a pressure fluid motor having a plurality of intermeshing rotors mounted in the same horizontal planes, and motor driven driving connections between said motor and said sprocket reversely connectible to said motor to drive said sprocket in opposite directions.
15. 2. A mining machine comprising cutting mechanism, feeding mechanism including a feed operating member, a pressure fluid motor operatively connected to said cutting mechanism and including a plurality of intermeshing rotors mounted in the same horizontal planes, and motor driven driving connections between said motor and said member reversely connectible to said motor to drive said member in opposite directions.
20. 3. A mining machine comprising cutting mechanism including a cutter chain carrying cutter bar and a cutter chain driving sprocket, feeding mechanism including a pressure fluid motor having a plurality of intermeshing rotors mounted in the same horizontal planes, and motor driven driving connections between said sprocket and said motor reversely connectible to said motor to drive said sprocket in opposite directions.
25. 4. A mining machine comprising cutting mechanism including a cutter chain carrying cutter bar and a cutter chain driving sprocket, feeding mechanism including a pressure fluid motor having a plurality of substantially longitudinally disposed intermeshing rotors mounted in the same horizontal planes, speed reducing mechanism connected to said sprocket, and motor driven driving connections between said speed reducing mechanism and said motor reversely connectible to said motor to drive said sprocket in opposite directions.
30. 5. A mining machine comprising cutting mechanism, feeding mechanism including a feed operating member, a pressure fluid motor operatively connected to said cutting mechanism and including a plurality of substantially longitudinally disposed intermeshing rotors mounted in the same horizontal planes, speed reducing mechanism on said frame connected to said feed operating member, and motor driven driving connections between said motor and said speed reducing mechanism.

ducing mechanism reversely connectible to drive said feed operating member in opposite directions.

6. A mining machine comprising cutting mechanism thereon including a cutter chain carrying cutter bar and a cutter chain driving sprocket, feeding mechanism including a feed operating member adjacent the opposite end of said machine from said bar, a pressure fluid motor on said machine including a plurality of intermeshing rotors mounted in the same horizontal planes, motor driven driving mechanism between said sprocket and said motor reversely connectible to said motor to drive said sprocket in opposite directions, and motor driven driving connections between said feed operating member and said motor.

7. A mining machine comprising cutting mechanism including a cutter chain carrying cutter bar, a cutter chain driving sprocket, and speed reducing mechanism for the latter, feeding mechanism including a feed operating member adjacent the opposite end of said machine from said bar, a pressure fluid motor on said machine including a pair of substantially longitudinally extending intermeshing rotors mounted in the same horizontal planes, motor driven driving mechanism between said speed reducing mechanism and said motor reversely connectible to the latter to drive said sprocket in opposite directions, and motor driven driving connections between said feed operating member and said motor.

8. A mining machine comprising cutting mechanism including a cutter chain carrying cutter bar and a cutter chain driving sprocket, feeding mechanism including a feed operating member adjacent the opposite end of said machine from said bar, a pressure fluid motor between said mechanisms including a plurality of intermeshing rotors mounted in the same horizontal planes, motor driven driving mechanism between said sprocket and one end of said motor reversely connectible to the latter to drive said sprocket in opposite directions, and motor driven driving connections between said feed operating member and the other end of said motor.

9. A mining machine comprising cutting mechanism including a cutter chain driving sprocket and speed reducing mechanism therefor, feeding mechanism including a feed operating member adjacent the opposite end of said machine from said bar, a pressure fluid motor on said machine between said cutting and feeding mechanisms including a plurality of substantially longitudinally disposed intermeshing rotors mounted in the same horizontal planes, motor driven driving mechanism between said speed reducing mechanism and one end of

said motor reversely connectible to the latter to drive said sprocket in opposite directions, and motor driven driving connections between said feed operating member and 5 the other end of said motor.

10. A mining machine comprising cutting mechanism including a cutter chain driving sprocket and speed reducing mechanism therefor, feeding mechanism including a 10 pressure fluid motor having a plurality of intermeshing rotors mounted in the same horizontal planes, motor driven driving connections between said motor and said speed reducing mechanism reversely connectible to 15 said motor to drive said sprocket in opposite directions, and means whereby the direction of feed of said machine may be varied as desired.

11. A mining machine comprising cutting 20 mechanism including a cutter chain driving sprocket and speed reducing mechanism therefor, feeding mechanism including a feed operating member and speed reducing mechanism therefor, a pressure fluid motor 25 between said mechanisms including a plurality of substantially longitudinally disposed intermeshing rotors mounted in the same horizontal planes, motor driven driving mechanism between said sprocket speed 30 reducing mechanism and one end of said motor reversely connectible to the latter to drive said sprocket in opposite directions, motor driven driving mechanism between said feed speed reducing mechanism 35 and the other end of said motor, and means whereby the direction of feed of said machine may be varied as desired.

12. A mining machine comprising cutting 40 mechanism including a cutter chain carrying cutter bar and a cutter chain driving sprocket, feeding mechanism including a pressure fluid motor having a plurality of intermeshing rotors disposed in the same horizontal planes, a gear located between 45 the axes of said rotors and connected to said sprocket, a pair of gears driven by different rotors and adjustable longitudinally relative to the axes of said rotors into engagement with said gear, and means for insuring alternate connection of said longitudinally 50 movable gears.

13. A mining machine comprising cutting 55 mechanism including a cutter chain carrying cutter bar and a cutter chain driving sprocket, feeding mechanism including a pressure fluid motor having a plurality of substantially longitudinally disposed intermeshing rotors disposed in the same horizontal planes, a gear located between the 60 axes of said rotors, speed reducing mechanism connected between said gear and said sprocket, a pair of gears driven by different rotors and adjustable longitudinally relative to the axes of said rotors into engagement 65 with said gear, and means for insur-

ing alternate connection of said longitudinally movable gears.

14. A mining machine slidable on a mine bottom comprising cutting mechanism, feeding mechanism, a motor intermediate said mechanisms including intermeshing rotors mounted in the same horizontal planes, and operative connections between said motor and said cutting and feeding mechanisms operative to drive said cutting mechanism in either direction and said feeding mechanism in one direction. 70

15. A mining machine slidable on a mine bottom comprising cutting mechanism, feeding mechanism, a motor intermediate said mechanisms including intermeshing rotors mounted in the same horizontal planes, and operative connections between said motor and said cutting and feeding mechanisms operative to drive said cutting mechanism in either direction and said feeding mechanism 75 in one direction. 80

16. A mining machine slidable on a mine bottom comprising cutting mechanism, feeding mechanism, a motor intermediate said mechanisms including intermeshing rotors mounted in the same horizontal planes, and operative connections between said motor and said cutting and feeding mechanisms operative to drive said cutting mechanism in either direction and said feeding mechanism 85 in one direction. 90

17. A mining machine slidable on a mine bottom comprising cutting mechanism, feeding mechanism, a motor intermediate said mechanisms including intermeshing rotors mounted in the same horizontal planes, and operative connections between the opposite ends of said motor and said cutting and feeding mechanisms operative to drive said cutting mechanism in either direction and said feeding mechanism 100 in one direction. 105

18. A mining machine slidable on a mine bottom comprising cutting mechanism, feeding mechanism, a motor intermediate said mechanisms including intermeshing rotors mounted in the same horizontal planes, and operative connections between the opposite ends of said motor and said cutting and feeding mechanisms operative to drive said cutting mechanism in either direction and said feeding mechanism in either direction. 110

19. A mining machine slidable on a mine bottom comprising cutting mechanism, feeding mechanism, a motor intermediate said mechanisms including intermeshing rotors mounted in the same horizontal planes, and operative connections between the opposite ends of said motor and said cutting and feeding mechanisms operative to drive said cutting mechanism in either direction and said feeding mechanism at different speeds in one direction. 115

20. A mining machine slidable on a mine 120

- bottom comprising cutting mechanism, feeding mechanism, a motor intermediate said mechanisms including intermeshing rotors disposed in the same horizontal planes, means for connecting either of said rotors to said cutting mechanism, and means for connecting one of said rotors to said feeding mechanism.
21. A mining machine slidable on a mine bottom comprising cutting mechanism, feeding mechanism, a motor intermediate said mechanisms including intermeshing rotors disposed in the same horizontal planes, means for connecting either of said rotors to said cutting mechanism, and means for connecting either of said rotors to said feeding mechanism.
22. A mining machine slidable on a mine bottom comprising cutting mechanism and feeding mechanism, a motor intermediate said mechanisms comprising intermeshing rotors disposed in the same horizontal planes, means for connecting either of said rotors to said cutting mechanism, and means for connecting one of said rotors to said feeding mechanism including speed varying mechanism.
23. A mining machine slidable on a mine bottom comprising cutting mechanism and feeding mechanism, a motor intermediate said mechanisms comprising intermeshing rotors disposed in the same horizontal planes, means for connecting either of said rotors to said cutting mechanism, and means for connecting either of said rotors to said feeding mechanism including speed varying mechanism.
24. A mining machine slidable on a mine bottom comprising cutting mechanism and feeding mechanism, a motor intermediate said mechanisms comprising intermeshing rotors disposed in the same horizontal planes, means for operatively connecting the same end of different rotors to said cutting mechanism, and means for operatively connecting the opposite end of one of said rotors to said feeding mechanism.
25. A mining machine slidable on a mine bottom comprising cutting mechanism and feeding mechanism, a motor intermediate said mechanisms comprising intermeshing rotors disposed in the same horizontal planes, means for operatively connecting the same end of different rotors to said cutting mechanism, and means for operatively connecting the opposite end of either of said rotors to said feeding mechanism.
26. A mining machine slidable on a mine bottom comprising cutting mechanism and feeding mechanism, a motor intermediate said mechanisms comprising intermeshing rotors disposed in the same horizontal planes, means for operatively connecting the same end of different rotors to said cutting mechanism, and means for operatively connecting the opposite end of either of said rotors to said feeding mechanism.
27. A mining machine slidable on a mine bottom comprising cutting mechanism and feeding mechanism, a motor intermediate said mechanisms comprising intermeshing rotors disposed in the same horizontal planes, means for operatively connecting the same end of different rotors to said cutting mechanism, and means for operatively connecting the opposite end of either of said rotors to said feeding mechanism including speed varying mechanism.
28. A mining machine slidable on a mine bottom comprising cutting mechanism including reduction mechanism, multi-speed feeding mechanism including a plurality of trains of reduction mechanism, a motor intermediate said cutting and feeding mechanisms including intermeshing rotors mounted in the same horizontal planes, means for operatively connecting the same end of either rotor to the reduction mechanism for said cutting mechanism, and means for connecting the opposite end of one rotor to either train of reduction mechanism for said feeding mechanism.
29. A mining machine slidable on a mine bottom comprising cutting mechanism including reduction mechanism, multi-speed feeding mechanism including a plurality of trains of reduction mechanism, a motor intermediate said cutting and feeding mechanisms including intermeshing rotors mounted in the same horizontal planes, means for operatively connecting the same end of either rotor to the reduction mechanism for said cutting mechanism, and means for connecting the opposite end of either rotor to either train of reduction mechanism for said feeding mechanism.
30. A mining machine slidable on a mine bottom comprising end frame sections respectively carrying cutting mechanism and feeding mechanism, a motor frame section intermediate said sections and rigidly connected thereto above its bottom carrying a motor comprising intermeshing rotors mounted in the same horizontal planes, means for operatively connecting either rotor to said cutting mechanism, and means for operatively connecting one of said rotors to said feeding mechanism.
31. A mining machine slidable on a mine bottom comprising end frame sections respectively carrying cutting mechanism and feeding mechanism, a motor frame section intermediate said sections and rigidly connected thereto above its bottom carrying a motor comprising intermeshing rotors mounted in the same horizontal planes, means for operatively connecting either rotor to said cutting mechanism, and means for operatively connecting one of said rotors to said feeding mechanism.

tor to said cutting mechanism, and means for operatively connecting either of said rotors to said feeding mechanism.

32. A mining machine slidable on a mine bottom comprising end frame sections respectively carrying cutting mechanism and feeding mechanism, a motor frame section intermediate said sections and rigidly connected thereto above its bottom carrying a motor comprising intermeshing rotors mounted in the same horizontal planes, means for operatively connecting the same end of either rotor to said cutting mechanism, and means for operatively connecting the opposite end of one of said rotors to said feeding mechanism.

33. A mining machine slidable on a mine bottom comprising end frame sections respectively carrying cutting mechanism and feeding mechanism, a motor frame section intermediate said sections and rigidly connected thereto above its bottom carrying a motor comprising intermeshing rotors mounted in the same horizontal planes, means for operatively connecting the same end of either rotor to said cutting mechanism, and means for operatively connecting the opposite end of either of said rotors to said feeding mechanism.

34. A mining machine slidable on a mine bottom comprising end frame sections respectively carrying cutting mechanism and feeding mechanism, a motor frame section intermediate said sections and rigidly connected thereto above its bottom carrying a longitudinally disposed motor comprising intermeshing rotors mounted in the same horizontal planes, means for operatively connecting the same end of either rotor to said cutting mechanism, and means for operatively connecting the opposite end of one of said rotors to drive said feeding mechanism at different speeds including a plurality of trains of mechanism.

35. A mining machine slidable on a mine bottom comprising end frame sections respectively carrying cutting mechanism and feeding mechanism, a motor frame section intermediate said sections and rigidly connected thereto above its bottom carrying a longitudinally disposed motor comprising intermeshing rotors mounted in the same horizontal planes, means for operatively connecting the same end of either rotor to said cutting mechanism, and means for operatively connecting the opposite end of either of said rotors to drive said feeding mechanism at different speeds including a plurality of trains of mechanism.

36. In a mining machine the combination of an elongated frame, a cutter bar projecting from one end thereof, a cutter chain carried by said bar, driving mechanism for said frame comprising a rotary pressure fluid motor having two intermeshing rotors

mounted in the same horizontal planes and each having a rotary shaft positioned substantially longitudinally of the frame and means for connecting alternately the said rotors with and disconnecting them from the said cutter chain.

37. A mining machine comprising, in combination, an elongated frame having a cutter bar at one end thereof, and a pressure fluid motor having two rotors, intermeshing, and having shafts extending substantially longitudinally of the elongated frame, and means for operatively connecting either of said shafts with said cutter chain for actuation thereof.

38. A mining machine comprising, in combination, an elongated frame having a cutter bar at one end thereof, said cutter bar carrying a cutter chain, and a pressure fluid actuator for said cutter chain comprising two intermeshing rotors turning in opposite directions, and means for connecting the shaft of one of said rotors to said cutter chain for actuation thereof in one direction and for connecting the other of said rotors to said cutter chain for actuation thereof in an opposite direction.

39. In a mining machine, the combination of a relatively elongated bed frame, a cutter bar at one end thereof, a cutting mechanism carried by said bar, a rotary feed element at the opposite end of said frame, a uni-directional pressure fluid actuated motor comprising two parallel intermeshing rotors positioned in the same horizontal planes and arranged substantially longitudinally of the frame, means at adjacent ends of the said rotors and driven thereby for driving the cutter chain, and means at the opposite adjacent ends of the rotors and actuated thereby for driving the machine feeding mechanism.

40. In a mining machine, the combination of an elongated bed frame having a cutter bar projecting from one end thereof, a cutter chain carried by said bar, a rotary element to feed the frame and mounted at the other end thereof, a uni-directional pressure fluid actuated motor on the frame intermediate of the cutting chain and the feed element for actuating them and comprising two intermeshing rotors positioned in horizontal planes and substantially longitudinally of the frame, means for transmitting power from one end of said motor to the said cutter chain, and means for driving said feeding mechanism from the other end of said motor, each of said driving means including independent reversing mechanisms respectively interposed between the motor and said feed mechanism and between said motor and said cutting mechanism.

41. In a mining machine, a cutter bar, cutting mechanism thereon, a motor comprising a plurality of oppositely moving

rotors, cutter driving mechanism, and means for connecting either one of said rotors to said driving mechanism.

42. In a mining machine, a cutter bar, cutting mechanism thereon, a motor comprising a plurality of oppositely moving rotors, cutter driving mechanism, and means for disconnecting one of said rotors and said driving mechanism and subsequently connecting the other rotor thereto. 10

43. In a mining machine, a cutter bar, cutting mechanism thereon, a motor comprising a plurality of oppositely moving rotors, cutter driving mechanism, and interlocking controlling mechanism for insuring the alternative connection of said rotors to said driving mechanism. 15

44. In a mining machine, a frame, cutting mechanism thereon, feeding mechanism thereon, a motor comprising a plurality of oppositely moving rotors, feed driving mechanism, and means for connecting either one of said rotors to said driving mechanism. 20

45. In a mining machine, a frame, cutting mechanism thereon, feeding mechanism thereon, a motor comprising a plurality of oppositely moving rotors, feed driving mechanism, and means for disconnecting one of said rotors and said driving mechanism 25 and subsequently connecting the other rotor thereto.

46. In a mining machine, a frame, cutting mechanism thereon, feeding mechanism thereon, a motor comprising a plurality of oppositely moving rotors, feed driving mechanism, and interlocking controlling mechanism for insuring the alternative connection of said rotors to said driving mechanism. 35

47. In a mining machine, a frame, cutting and feeding mechanisms thereon, a motor comprising a plurality of oppositely moving rotors, driving means for said cutting and feeding mechanisms, and means for connecting either one of said rotors to either of said mechanisms. 40

48. In a mining machine, a frame, cutting and feeding mechanisms thereon, a motor comprising a plurality of oppositely moving rotors, driving means for said cutting and feeding mechanisms, and means for disconnecting one of said rotors from one of said mechanisms and subsequently connecting the other rotor thereto. 50

49. In a mining machine, cutting mechanism, feeding mechanism, a motor comprising a plurality of oppositely moving rotors, driving means for said cutting and feeding mechanisms, and interlocking controlling mechanism for insuring the alternative connection of said rotors to one of said mechanisms. 55

50. In a mining machine, a motor including a plurality of oppositely rotating rotors, cutting and feeding mechanisms disposed 60

at the opposite ends thereof, means for connecting one end of one of said rotors to one of said mechanisms and disconnecting the same end of the other therefrom, and means for similarly changing the connections of the other mechanism. 70

51. In a mining machine, cutting and feeding mechanisms, a motor operatively connected thereto, clutch mechanism disposed between said motor and said cutting mechanism, and clutch controlling mechanism including a reciprocable member and an eccentric rotatable thereon to lock the latter and the clutch mechanism in a desired position. 75

52. A mining machine comprising cutting mechanism, feeding mechanism connectible to feed the machine at a plurality of speeds, friction mechanism operatively connected to said feeding mechanism, controlling means 80 for said feeding mechanism including a controlling member, controlling mechanism for said friction including a controlling member, and interlocking connections between said controlling members whereby said feed controlling member may not be moved from one position without first releasing the friction and whereby said friction may not be applied when said controlling member is in that position. 85

53. A mining machine comprising cutting mechanism including a cutter chain driving sprocket, a pressure fluid motor comprising a casing housing a plurality of intermeshing rotors mounted in the same horizontal planes, a second casing between said sprocket and said motor, speed reducing mechanism operatively connected to said sprocket, and means carried in said second casing connected to said speed reducing mechanism and 100 reversely connectible to said motor for rotating said sprocket in opposite directions. 105

54. A mining machine comprising cutting mechanism including a cutter chain driving sprocket, a pressure fluid motor comprising a casing housing a plurality of intermeshing rotors mounted in the same horizontal planes, a second casing between said motor and said sprocket and having a lubricant chamber formed therein, speed reducing 110 mechanism operatively connected to said sprocket, and means including gearing in said lubricant chamber connected to said speed reducing mechanism and reversely connectible to said motor for rotating said 115 sprocket in opposite directions. 120

55. A mining machine comprising cutter mechanism including a cutter chain driving sprocket, a pressure fluid motor driving 123 said sprocket, means for supplying pressure fluid to said motor including a passage having an inlet adjacent said sprocket and means on said machine for supplying lubricant to the pressure fluid passing to said motor including a lubricant reservoir. 130

- municating with said passage and mechanism operative to admit pressure fluid from said supply to said reservoir and to discharge lubricant from said reservoir to said pressure fluid supply. 5
56. A mining machine comprising cutting mechanism including a pivoted cutter chain carrying cutter bar and a cutter chain driving sprocket, driving mechanism therefor including a pressure fluid motor adjacent said sprocket, means for supplying pressure fluid to said motor including a passage communicating therewith and having a plurality of supply connections located on opposite sides of the machine center line, and means for supplying pressure fluid to said passage including a hose connection selectively connectible with either of said oppositely located supply connections in different 15 positions of said bar. 15
57. A mining machine comprising cutting mechanism including a pivoted cutter chain carrying cutter bar and a cutter chain driving sprocket, driving mechanism therefor including a pressure fluid motor adjacent said sprocket, means for supplying pressure fluid to said motor including a passage communicating therewith and having a plurality of supply connections located on opposite sides of the machine center line, means for supplying pressure fluid to said passage including a hose connection selectively connectible with either of said oppositely located connections in different positions of 25 said bar, and clutch mechanism controlling the connection of said sprocket to said motor and disposed adjacent said sprocket and between said supply connections. 30
58. A mining machine comprising driving mechanism including a pressure fluid motor having a plurality of intermeshing rotors mounted in the same horizontal planes, cutting mechanism including a cutter chain driving sprocket, sprocket driving mechanism driven by said motor, and means for supporting said sprocket driving mechanism including a bearing housed in an adjacent 40 end of a rotor. 45
59. A mining machine comprising cutting mechanism, cutter driving mechanism including a pressure fluid motor having a plurality of intermeshing rotors mounted in the same horizontal planes, feeding mechanism including a feed operating member, driving mechanism between said motor and said feed operating member, and supporting means for said mechanism including a bearing housed in an adjacent end of a rotor. 55
60. A mining machine comprising, cutting mechanism including a cutter chain driving sprocket, feeding mechanism including a feed operating member, a pressure fluid motor between said mechanisms including a plurality of intermeshing rotors 60 mounted in the same horizontal planes, driv- ing mechanism between the opposite ends of said motor and said mechanisms, and supporting means for said driving mechanisms including bearings housed in the opposite ends of said rotors. 70
61. A mining machine comprising cutting mechanism and driving mechanism therefor including a plurality of intermeshing rotors mounted in the same horizontal planes and a rotor bearing extending into the end of one 75 of said rotors. 75
62. A mining machine comprising cutting mechanism and driving mechanism therefor including a plurality of intermeshing rotors mounted in the same horizontal planes and 80 rotor bearings extending into the same end of each of said rotors. 80
63. A mining machine comprising cutting mechanism, feeding mechanism, and driving mechanism intermediate said mechanisms including a motor having intermeshing rotors mounted in the same horizontal planes and a rotor bearing extending into one end 85 of one of said rotors. 85
64. A mining machine comprising cutting mechanism, feeding mechanism, and driving mechanism intermediate said mechanisms including a motor having intermeshing rotors mounted in the same horizontal planes and rotor bearings extending into the same 90 end of each of said rotors. 90
65. A mining machine comprising cutting mechanism, feeding mechanism, and driving mechanism intermediate said mechanisms including a motor having intermeshing rotors mounted in the same horizontal planes and bearings extending into opposite ends 100 of said rotors. 100
66. A mining machine comprising feeding mechanism including a pressure fluid 105 motor having a casing and a plurality of intermeshing rotors therein mounted in the same horizontal planes, cutting mechanism operatively connected to said motor, and pressure supply connections for said motor 110 disposed within the lateral limits of said motor casing. 110
67. A mining machine slidable on a mine bottom comprising feeding mechanism including a feed operating member, cutting 115 mechanism including a cutter chain sprocket, driving mechanism therefor therebetween including a longitudinally disposed pressure fluid motor having a casing and horizontal rotor means therein connected to said member and sprocket, and pressure supply means for said motor disposed within the lateral 120 limits of said casing and extending to a point above said sprocket and accessible 125 from that end of the machine. 125
68. A mining machine slidable on a mine bottom comprising cutting mechanism including a cutter chain sprocket, feeding mechanism including a feed operating member, driving mechanism therefor therebe- 130

5 tween including a horizontal pressure fluid motor, and pressure fluid supply means for said motor disposed within the lateral limits of said machine and extending to points above and on opposite sides of said sprocket and accessible from that end of the machine.

10 69. A mining machine comprising feeding mechanism including a pressure fluid motor having a casing and a plurality of intermeshing rotors therein mounted in the same horizontal planes, cutting mechanism operatively connected to said motor, and pressure supply and relief connections for said motor disposed within the lateral limits 15 of said motor casing.

20 70. A mining machine comprising cutting and feeding mechanism including a pressure fluid driving motor having a casing and a plurality of intermeshing rotors therein mounted in the same horizontal planes, and separate pressure supply and relief connections for said motor carried on said machine and respectively connectable to a supply line and communicating with the atmosphere.

25 71. A mining machine comprising cutting and feeding mechanism including a pressure fluid motor having a casing and a plurality of intermeshing rotors therein mounted in the same horizontal planes, and pressure supply and relief connections for said motor carried on said machine within the lateral limits thereof and respectively connectable to a supply line and communicating with the atmosphere.

30 72. A mining machine comprising cutting and feeding mechanism including a pressure fluid motor having a longitudinally disposed casing and a plurality of intermeshing rotors therein mounted in the same horizontal planes, and pressure supply and relief connections therefor on said machine disposed within the lateral limits of said motor casing and respectively connectable to a supply line and communicating with the atmosphere.

35 73. A mining machine comprising feeding mechanism, cutting mechanism, a pressure fluid motor on said frame between said mechanisms operatively connected thereto including a casing and a plurality of intermeshing rotors therein mounted in the same horizontal planes, and pressure supply and relief connections for said motor disposed within the lateral limits of said motor casing.

40 74. A mining machine comprising feeding mechanism, cutting mechanism, a pressure fluid motor between said mechanisms and operatively connected thereto including a longitudinally disposed casing and a plurality of intermeshing rotors therein mounted in the same horizontal planes, and pressure supply and relief connections for said motor disposed within the lateral limits of 45 said motor casing.

75. A mining machine comprising feeding mechanism, cutting mechanism, a pressure fluid motor between said mechanisms and operatively connected thereto including a casing and a plurality of intermeshing rotors therein mounted in the same horizontal planes, and separate pressure supply and relief connections for said motor carried on said machine and respectively connectable to a supply line and communicating with the atmosphere.

80 76. A mining machine comprising feeding mechanism, cutting mechanism, a pressure fluid motor between said mechanisms and operatively connected thereto including a casing and a plurality of intermeshing rotors therein mounted in the same horizontal planes, and separate pressure supply and relief connections for said motor at one end thereof and within the lateral limits thereof and respectively connectable to a supply line and communicating with the atmosphere.

85 77. A mining machine comprising feeding means including a pressure fluid motor thereon having a casing and a plurality of intermeshing rotors therein mounted in the same horizontal planes, cutting mechanism operatively connected to said motor, means for supplying pressure fluid to said motor inlet including a passage in one of the end walls of said motor casing, and a motor relief valve on said frame communicating with said inlet through one of the end walls of said casing.

90 78. A mining machine comprising feeding means including a pressure fluid motor having a casing and a plurality of intermeshing rotors therein mounted in the same horizontal planes, cutting mechanism connected to said motor, means for supplying pressure fluid to said motor including a head having an inlet and a communicating chamber communicating with the motor inlet, and a relief valve carried on said head and communicating with said chamber.

95 79. A mining machine comprising cutting mechanism, feeding mechanism, a pressure fluid motor operatively connected thereto including a casing member and suitably journaled intermeshing rotors cooperating therewith, a pressure supply connection for said motor, and means including a relief valve for eliminating contact between said rotors and casing member and wear on the rotor bearings upon shutting off said pressure supply to interrupt cutting or feeding.

105 80. A mining machine comprising cutting mechanism, feeding mechanism, and pressure fluid driving mechanism therefor therebetween including intermeshing rotors journaled in the same horizontal planes and a cooperating casing member, a pressure supply connection for said motor, and means including a relief valve for eliminating contact between said rotors and casing member.

and wear on the rotor bearings upon shutting off said pressure supply to interrupt cutting or feeding.

81. A mining machine comprising cutting mechanism, feeding mechanism, a pressure fluid motor disposed longitudinally of said machine and operatively connected to said mechanisms including a horizontal casing member and a plurality of intermeshing rotors mounted in the same horizontal planes, a connection for supplying pressure fluid to said motor, and means for directing exhaust fluid pressure laterally from said motor having baffle mechanism operative to prevent the passage of refuse to said rotors.

82. A mining machine comprising cutting mechanism, feeding mechanism, a pressure fluid motor disposed longitudinally of said machine and operatively connected to said mechanisms including a horizontal casing member and a plurality of intermeshing rotors mounted in the same horizontal planes, a connection for supplying pressure fluid to said motor, and means for directing exhaust fluid pressure laterally from said motor having provision for directing the exhaust away from the mine bottom.

83. A mining machine comprising cutting mechanism, feeding mechanism, a pressure fluid motor therebetween disposed longitudinally of said machine and operatively connected to said mechanisms including a horizontal casing member and a plurality of intermeshing rotors mounted in the same horizontal planes, means for supplying pressure fluid to said motor, and means for directing exhaust fluid pressure therefrom having provision for directing the exhaust laterally including baffle mechanism operative to prevent the passage of refuse to said rotors.

84. A mining machine comprising cutting and feeding mechanism, a pressure fluid motor operatively connected to said mechanisms and including a casing providing a rotor chamber and rotor means in said chamber, means for supplying pressure fluid to said motor, and means for exhausting fluid pressure therefrom including an exhaust passage formed in the upper surface of the motor casing and a cooperating baffle so disposed that refuse falling into said passage may not enter the rotor chamber and will be blown out by the exhaust.

85. A mining machine slidable on a mine bottom comprising feeding mechanism including a feed operating member having its axis disposed in the longitudinal center line of said machine, cutting mechanism including a cutter chain driving sprocket having its axis disposed in the longitudinal center line of said machine, a motor intermediate said mechanisms including a rotor disposed at one side of the longitudinal center line of the machine and parallel thereto, and

driving connections between the opposite ends of said rotor and said sprocket and said feed operating member.

86. A mining machine slidable on a mine bottom comprising oppositely disposed end frame sections, one carrying cutting mechanism including a cutter chain driving sprocket and the other carrying the feed operating member, a motor frame section intermediate said sections and rigidly connected thereto above its bottom carrying a rotor disposed at one side of the longitudinal center line of said section and parallel thereto, and means operatively connecting the opposite ends of said rotor to said sprocket and said operating member.

87. A mining machine slidable on a mine bottom comprising a motor, cutting mechanism at one end thereof driven by said motor and including a pivoted laterally extending cutter chain carrying cutter bar and a cutter chain driving sprocket, and feeding mechanism at the opposite end thereof driven by said motor and including a feed operating member, a flexible feeding member cooperating therewith and presenting a plurality of flexible portions having free extremities, means whereby either portion may be drawn in at a cutting speed without reversing said motor, and guiding means for each flexible portion adjacent said operating member for maintaining the pull on said flexible portions in a plane substantially coincident with the plane of said sprocket.

88. A mining machine slidable on a mine bottom comprising a motor, cutting mechanism driven thereby and at one end thereof including a pivoted laterally extending cutter bar, a cutter chain thereon and a cutter chain driving sprocket, and feeding mechanism driven by said motor and at the opposite end thereof including a feed operating member, a flexible feeding member cooperating therewith and presenting a plurality of flexible portions having free extremities, means whereby either portion may be drawn in at a cutting speed without reversing said motor, and guiding means for each flexible portion adjacent said operating member for maintaining the pull on said flexible portions in a plane below the uppermost surface of said bar.

89. A mining machine slidable on its bottom on a mine bottom, comprising a motor between the ends thereof, feeding mechanism including a feed operating member on one end of said machine operatively connected to one end of said motor, cutting mechanism on the opposite end of said machine operatively connected to the opposite end of said motor and including a pivoted cutter bar disposable laterally at one side of said machine, guiding means including a rotatable guiding member at one edge of said machine adjacent said operating mem-

- ber, and a single flexible feeding member cooperating with said feed operating member and guiding means and having one end fixed at a point in advance of the machine and adjacent the face and its end on the opposite side of said feed operating member lying loose. 65
90. A mining machine slidable on its bottom on a mine bottom, comprising a motor between the ends thereof, feeding mechanism including a feed operating member on one end of said machine operatively connected to one end of said motor, cutting mechanism on the opposite end of said machine operatively connected to the opposite end of said motor and including a pivoted cutter bar disposable laterally at either side of said machine, guiding means including rotatable guiding members on opposite edges of said machine adjacent said operating member, and a single flexible feeding member cooperating with said feed operating member and either of said guiding means and in either position of said bar having one end fixed at a point in advance of the machine and adjacent the face and its end on the opposite side of said feed operating member lying loose. 75
91. A mining machine slidable on its bottom on a mine bottom comprising a longitudinally disposed horizontal motor intermediate the ends thereof and including intermeshing rotors disposed in the same horizontal planes, cutting and feeding mechanisms at opposite ends thereof and including respectively a pivoted cutter chain carrying bar having a sprocket, and a feed operating member each rotatable on vertical axes substantially in the machine center line, driving means for rotating said sprocket in either direction from one end of said motor and said feed operating member at different speeds from the opposite end thereof, and flexible feeding and guiding means including a flexible member cooperating with said feed operating member and when said bar is laterally disposed under the face at either side extending in a single stationary strand to an anchor in advance of the feed operating end of the machine. 80
92. The combination with a mining machine, of feeding mechanism including a friction device and a feed reversing mechanism, pivoted controlling members for each of the same movable in substantially parallel planes, and interlocking connections between said friction and reverse controlling members. 85
93. The combination with a mining machine, of feeding mechanism including a friction device and a feed reversing mechanism, controlling members for each of the same, and means for inhibiting the operation of said reverse controlling member prior to movement of said friction controlling member to releasing position. 90
94. The combination with a mining machine, of a feed operating member and driving mechanism therefor including a frictional controlling mechanism having a controlling member and a reversing mechanism having a controlling member, and controlling connections for said frictional mechanism necessarily operative to remove the load from said reversing mechanism before its controlling member can be moved from either of its positions into the other and only operative to apply the load thereto when said reverse controlling member is out of one reversing position. 95
95. In a mining machine, the combination with feeding mechanism having provision for relatively fast and slow speeds and including a yielding element, of a controlling member and connections for controlling the feeding speed, a controlling member and connections for increasing the resistance to yielding opposed by said element, and means carried by said last named member for locking said first named member against operation. 100
96. In a mining machine, the combination with feeding mechanism having provision for relatively fast and slow speeds and including a yielding element, of a controlling member and connections for controlling the feeding speed, and a controlling member and connections for increasing the resistance to yielding opposed by said element, said last named member having a shoulder adapted to engage and lock said first named member. 105
97. In a mining machine, the combination with feeding mechanism having provision for relatively fast and slow speeds and including a friction device, of a controlling member and connections for controlling the feeding speed, and an operating member and connections for loading said friction device, said operating member having a shoulder adapted to engage and lock said controlling member and thereby prevent loading of said friction device. 110
98. In a mining machine, the combination with feeding mechanism having provision for relatively fast and slow speeds and including a yielding element, of means for controlling the feeding speed, an eccentric for operating said controlling means, a shaft for turning said eccentric, a manually operable lever and connections for turning said shaft, and a controlling member and connections for increasing the resistance to yielding opposed by said element, said last named member having a shoulder adapted to engage and lock said manually operable lever. 115
99. A mining machine slidable on a mine

- bottom comprising flexible feeding mechanism including a plurality of flexible feeding portions having free extremities, a motor having a longitudinally disposed power shaft, and means driven by one end of said motor and disposed wholly at the same side of a transverse plane at the other end of said motor as said first mentioned end thereof and selectively connectible thereto to draw in either portion at different speeds including a predetermined cutting speed, all with the motor running in the same direction.
104. A mining machine slidable on a mine bottom comprising cutting mechanism at one end thereof, a motor having one end connected to said cutting mechanism, and flexible feeding mechanism at the opposite end of said machine including portions having free extremities and driving connections selectively connectible with the opposite end of said motor whereby either of said portions may be drawn in, at a predetermined cutting speed without reversing said motor, each of said connections having provision for release on overload and manual reduction of the speed thereof.
105. A mining machine slidable on a mine bottom comprising flexible feeding mechanism including a plurality of flexible feeding portions having free extremities, a motor, and means driven thereby and including elements selectively connectible thereto for drawing in, with the motor running in the same direction in each case either portion at a predetermined cutting speed and a predetermined higher speed substantially in excess of the maximum potential cutting speed of said machine under normal working conditions.
106. A mining machine slidable on a mine bottom comprising flexible feeding mechanism including a plurality of flexible feeding portions having free extremities, a motor, and means driven thereby and including elements selectively connectible thereto for drawing in, with the motor in each case running in the same direction either portion at a predetermined cutting speed and a predetermined higher speed and also including automatically releasable friction mechanism and manually controllable means for reducing said speed at will.
107. A mining machine slidable on a mine bottom comprising a cutter frame section carrying a cutter bar, a feed frame section, a motor frame section disposed between said sections connected thereto at points above its bottom and carrying a motor driving said cutting mechanism, and means carried on said feed frame section and including a plurality of flexible feeding portions whereby said bar may be sumped into a face by drawing in one portion at a predetermined cutting speed and thereafter with the motor still running in the same direction fed transversely of the face along the other portion at a predetermined cutting speed.
108. A mining machine slidable on a mine bottom comprising a motor, cutting mechanism adapted to be reversibly driven thereby including a cutter bar, and flexible feeding mechanism operable to feed said machine for lateral cutting operations in opposite directions along a face including a plurality of flexible feeding portions having free extremities and means subject to fric-
101. A mining machine slidable on a mine bottom comprising flexible feeding mechanism including a plurality of flexible feeding portions having free extremities, a driving motor therefor disposed longitudinally of said machine, and mechanical means driven by one end of said motor disposed wholly at the same side of a transverse plane at the other end of said motor as said first mentioned end whereby without reversal of the motor either portion may be drawn in at different speeds including a predetermined cutting speed.
102. A mining machine slidable on a mine bottom comprising flexible feeding mechanism including a plurality of flexible feeding portions, a driving motor therefor disposed longitudinally of said machine, and mechanical means driven by one end of said motor and disposed at the same end thereof and including friction mechanism and manually controlled means whereby either of said portions may be drawn in at a predetermined cutting speed or at a slower speed and each feed automatically released upon overload.
103. A mining machine slidable on a mine bottom comprising cutting mechanism at one end thereof, a motor having one end connected to said cutting mechanism, and flexible feeding mechanism at the opposite end of said machine including portions having free extremities and driving connections selectively connectible with the opposite end of said motor whereby either of said portions may be drawn in at a predetermined cutting speed without reversing said motor.

tional control whereby during said reverse cutting operations said bar may be sumped into a face by drawing in a different portion at one of a plurality of speeds including a 5 predetermined cutting speed and subsequently with the motor running in the same direction as before moved transversely of the face along the other portion at one of a plurality of speeds including 10 a predetermined cutting speed while the first mentioned portion lengthens.

109. A mining machine slidable on a mine bottom comprising cutting mechanism including a pivoted cutter bar at one end of 15 said machine adjustable into lateral or longitudinal positions, and means including a plurality of flexible feeding portions at the opposite end of said machine whereby said bar may be sumped into the face when disposed in either position and thereafter moved bodily laterally along the face without reversing or interrupting the drive of 20 said cutting mechanism.

110. A mining machine slidable on a mine 25 bottom comprising cutting mechanism at one end thereof including a pivoted cutter bar disposable in a fixed lateral position, and flexible feeding mechanism at the opposite end thereof including a plurality of flexible 30 feeding portions having free extremities and operative connections whereby without reversing or interrupting the drive of said cutting mechanism and when said bar is so disposed said machine may be moved bodily 35 along one portion in such manner as to bring the bar under the face at a predetermined cutting speed and then moved bodily along the other portion and the face at a predetermined cutting speed.

111. A mining machine slidable on a mine bottom comprising cutting mechanism at one end thereof including a pivoted cutter bar disposable in a fixed lateral position at either 40 side of the machine, and flexible feeding 45 mechanism at the opposite end thereof including a plurality of flexible feeding portions having free extremities and operative connections whereby without reversing said cutting mechanism or interrupting the drive 50 thereof and when said bar is disposed in either lateral position said machine may be moved bodily along one portion in such manner as to bring the bar under the face at one of a plurality of speeds including a 55 predetermined cutting speed and then moved bodily along the other portion and the face at one of a plurality of speeds including a predetermined cutting speed.

112. A mining machine slidable on a mine 60 bottom comprising a frame, a motor thereon, cutting mechanism driven by said motor and disposed at one end of said frame including a cutter bar pivotally connected to 65 said frame and disposable laterally or longitudinally relatively thereto, and flexible feed-

ing mechanism disposed at the opposite end of said frame including a plurality of flexible feeding portions and operative connections whereby without reversing or interrupting the drive of said cutting mechanism said bar 70 when longitudinally disposed may be moved longitudinally into a face at a predetermined cutting speed along one portion and when laterally disposed may be moved transversely of said face at a predetermined 75 cutting speed along the other portion.

113. A mining machine slidable on a mine bottom comprising a motor, cutting mechanism driven thereby and disposed at one end of said machine including a pivotally connected cutter bar disposable laterally or longitudinally, and flexible feeding mechanism driven by said motor and disposed at the opposite end of said machine including a plurality of flexible portions having free 80 extremities and operative connections operative without reversing said cutting mechanism or interrupting the drive thereof for sumping said bar when laterally or longitudinally disposed at a predetermined cutting speed along one portion and thereafter moving the same laterally relative to a face 85 and at a predetermined cutting speed along the other portion.

114. A mining machine slidable on a mine bottom comprising a motor, rotatable cutting mechanism reversibly driven thereby and disposed at one end of said machine including a pivotally connected cutter bar disposable laterally or longitudinally, and flexible feeding mechanism driven by said motor and disposed at the opposite end of said machine including a plurality of flexible portions having free extremities 90 and operative connections operative in either direction of rotation of said cutting mechanism and without reversing the latter or interrupting the drive thereof for sumping said bar when laterally or longitudinally disposed at a predetermined cutting speed along one portion and thereafter moving the same laterally relative to a face 95 and at a predetermined cutting speed along the other portion.

115. A mining machine slidable on a mine bottom comprising a motor, cutting mechanism driven thereby and disposed at one end of said machine including a pivotally connected cutter bar disposable laterally or longitudinally, and flexible feeding mechanism therefor at the opposite end of said machine and including a plurality of flexible feeding portions having free extremities and operative connections for drawing in either of said portions at a predetermined cutting speed with said motor rotating in each case in the same direction.

116. A mining machine slidable on a mine bottom comprising cutting mechanism including an operatively connected cutter bar 125

carrying a cutter chain, a motor driving said cutting mechanism arranged longitudinally of said machine, and flexible feeding mechanism including a plurality of flexible feeding portions having free extremities and operative connections driven wholly by the end of said motor remote from said cutter bar whereby with the motor running in the same direction and without reversing or reducing the speed of the cutter chain either portion may be drawn in at any one of a plurality of speeds including a predetermined cutting speed.

117. A mining machine slidable on a mine bottom comprising cutting mechanism at one end thereof including an operatively connected cutter bar carrying a cutter chain, a motor intermediate the ends of said machine driving said cutting mechanism, and flexible feeding mechanism at the opposite end of said machine including a plurality of flexible feeding portions having free extremities and operative connections whereby with the motor running in the same direction and without reversing or reducing the speed of the cutter chain either portion may be drawn in at any one of a plurality of speeds including a predetermined cutting speed.

118. A mining machine slidable on a mine bottom comprising a motor disposed longitudinally of said machine, cutting mechanism driven thereby, and flexible feeding mechanism including a plurality of flexible feeding portions having free extremities, means driven by the end of said motor remote from said cutting mechanism for drawing in one of said portions at a predetermined cutting speed while the other lengthens at substantially the same speed, and means connectible at will with the same end of said motor for drawing in said other portion at a plurality of speeds including a predetermined cutting speed and a higher speed substantially in excess of the maximum potential cutting speed of said machine while the motor rotates as before.

119. A mining machine slidable on a mine bottom comprising cutting mechanism at one end thereof, feeding mechanism at the opposite end thereof and including a rotatable feed chain sprocket, a motor intermediate said mechanisms operatively driving said cutting mechanism, a continuous flexible feed chain engaging said sprocket and presenting a plurality of flexible feeding portions having free extremities, and means between said motor and said sprocket operative with said motor running in the same direction in either case to draw in either of said portions at a predetermined cutting speed.

120. A mining machine slidable on a mine bottom comprising cutting mechanism at one end thereof, feeding mechanism at

the opposite end thereof and including a rotatable feed chain sprocket, a motor intermediate said mechanisms operatively driving said cutting mechanism, a continuous flexible feed chain engaging said sprocket and presenting a plurality of flexible feeding portions, and means between said motor and said sprocket and operative with said motor in each case running in the same direction to draw in either of said portions at a predetermined cutting and at a higher predetermined speed.

121. A mining machine slidable on a mine bottom comprising a motor, cutting mechanism including a cutter bar, flexible feeding mechanism including a plurality of flexible feeding portions having free extremities, and operative connections whereby with said motor in each case running in the same direction said cutting mechanism may be driven in opposite directions and either of said flexible portions drawn in by power.

122. A mining machine slidable on a mine bottom comprising a motor, cutting mechanism including a cutter bar, flexible feeding mechanism including a plurality of flexible feeding portions having free extremities, and operative connections whereby with said motor in each case running in the same direction said cutting mechanism may be driven in opposite directions and either of said flexible portions drawn in by power at a plurality of speeds including a predetermined cutting speed.

123. A mining machine slidable on a mine bottom comprising a motor, cutting mechanism including a cutter bar, flexible feeding mechanism including a flexible feeding member, and operative connections whereby with said motor in each case running in the same direction said cutting mechanism may be driven in opposite directions and said flexible feeding member drawn in at different speeds in either direction of drive of said cutting mechanism.

124. A mining machine slidable on a mine bottom comprising a motor, cutting mechanism including a cutter bar, operative connections whereby with like rotation of said motor said cutting mechanism may be driven in opposite directions, and flexible feeding mechanism including a plurality of flexible feeding portions having free extremities and provision for varying the length of either of said portions.

125. A mining machine slidable on a mine bottom comprising a motor including a plurality of intermeshing rotors, cutting mechanism including a cutter chain carrying cutter bar, flexible feeding mechanism including a feed operating member and a co-operating flexible feeding member, and operative connections whereby with like rotation of said motor said cutter chain may be

reversely driven by different rotors while said feed operating member is rotatable at will in only one direction by one rotor.

126. A mining machine slidable on a mine bottom comprising a motor including a plurality of intermeshing rotors, cutting mechanisms including a cutter chain carrying cutter bar, flexible feeding mechanism including a plurality of flexible feeding portions having free extremities, and operative connections whereby with like rotation of said motor said cutter chain may be driven in opposite directions from different rotors and said feeding mechanism reversely actuated from different rotors to draw in different portions.

127. A mining machine slidable on a mine bottom comprising a motor including a plurality of intermeshing rotors, cutting mechanism including a cutter chain carrying cutter bar, flexible feeding mechanism including a feed operating member and a cooperating flexible feeding portion having a free extremity, and operative connections whereby with like rotation of said motor said cutter chain may be driven thereby in opposite directions and said feed operating member may be driven by said motor at a predetermined cutting speed or at a higher speed.

128. A mining machine slidable on a mine bottom comprising a longitudinally extending horizontally disposed motor, cutting mechanism driven by said motor including a cutter chain carrying cutter bar projecting from said machine at one end of said longitudinally extending motor, and flexible feeding mechanism therefor at and operatively connected to the opposite end of said motor including a plurality of flexible feeding portions having free extremities and operative connections for at will drawing in either of said portions at a predetermined cutting speed without reversing or interrupting the drive of said cutting mechanism.

129. A mining machine slidable on a mine bottom comprising a longitudinally extending horizontally disposed motor, cutting mechanism reversely driven by said motor including a cutter chain carrying cutter bar projecting from said machine at one end of said longitudinally extending motor, and flexible feeding mechanism therefor at and operatively connected to the opposite end of said motor including a plurality of flexible feeding portions having free extremities and operative connections operative during either direction of rotation of said cutter chain to draw in either portion at a predetermined cutting speed and having provision for at will drawing in either of said portions at a predetermined higher speed while said cutter chain is rotating in either direction or at different speeds form-

130. A mining machine slidable on a mine bottom comprising a longitudinally extending horizontally disposed motor, cutting mechanism reversely driven by said motor including a cutter chain carrying cutter bar projecting from said machine at one end of said longitudinally extending motor, and flexible feeding mechanism therefor at and operatively connected to the opposite end of said motor including a plurality of flexible feeding portions having free extremities and operative connections operative during either direction of rotation of said cutter chain to draw in either portion at a predetermined cutting speed and having provision for at will drawing in either of said portions at a predetermined higher speed while said cutter chain is rotating in either direction or at speeds forming a fraction of said predetermined cutting speed or a fraction of said predetermined higher speed.

131. A mining machine slidable on a mine bottom comprising a motor disposed longitudinally of said machine, cutting mechanism driven by said motor and including a cutter bar, and flexible feeding mechanism driven by the end of said motor which is more remote from the outer end of said cutter bar including a plurality of flexible feeding portions having free extremities and operative connections arranged wholly at the last mentioned end of said motor whereby with the motor in each case rotating in the same direction either of said portions may be drawn in at a predetermined cutting speed and one of said portions drawn in when desired at a higher speed.

132. A mining machine slidable on a mine bottom comprising a motor disposed longitudinally of said machine, cutting mechanism driven by said motor and including a cutter bar, and flexible feeding mechanism driven by the end of said motor which is more remote from the outer end of said cutter bar including a plurality of flexible feeding portions having free extremities and operative connections arranged wholly at the last mentioned end of said motor whereby with the motor in each case rotating in the same direction either of said portions may be drawn in at a predetermined cutting speed and the other portion drawn in when desired at a higher speed, said operative connections including mechanism for permitting lengthening of said other portion while said first mentioned portion is drawn in during crossing a face.

133. A mining machine slidable on a mine bottom comprising a motor, cutting mechanism driven by said motor, and flexible feeding mechanism driven by said motor including a plurality of flexible feeding portions having free extremities and operative con-

nections operable at different times to draw in different portions whereby with the motor in each case rotating in the same direction either of said portions may be drawn in at a predetermined cutting speed and the other portion drawn in when desired at a higher speed substantially in excess of the maximum cutting speed of said machine; said operative connections including mechanism for permitting lengthening of said other portion while the first mentioned portion is drawn in.

134. A mining machine slidable on a mine bottom comprising a motor, cutting mechanism operatively connected thereto and including a cutter bar, and flexible feeding mechanism for feeding said bar longitudinally into a face and laterally along the same including a plurality of flexible feeding portions having free extremities and variable speed mechanism including manually adjustable friction mechanism and operatively connected to said motor whereby with the motor in each case rotating in the same direction either of said portions may be drawn in at any of a plurality of speeds including a predetermined cutting speed.

135. A mining machine slidable on a mine bottom comprising a motor, cutting mechanism operatively connected thereto and including a cutter bar, and flexible feeding mechanism for feeding said bar longitudinally into a face and laterally along the same including a plurality of flexible feeding portions having free extremities and variable speed mechanism including manually adjustable friction mechanism and operatively connected to said motor whereby with the motor in each case rotating in the same direction either of said portions may be drawn in at any of a plurality of speeds including a predetermined cutting speed and a predetermined higher speed.

136. A mining machine slidable on a mine bottom comprising a motor, cutting mechanism operatively connected thereto and including a cutter bar, and flexible feeding mechanism for feeding said bar longitudinally into a face and laterally along the same including a plurality of flexible feeding portions having free extremities and variable speed mechanism including manually adjustable friction mechanism and operatively connected to said motor whereby with the motor in each case rotating in the same direction either of said portions may be drawn in at any of a plurality of speeds including a predetermined cutting speed or at a fractional speed determined by the adjustment of said friction mechanism.

137. A mining machine slidable on a mine bottom comprising a motor, cutting mechanism operatively connected thereto and including a cutter bar, and flexible feeding mechanism for feeding said bar longitudi-

nally into a face and laterally along the same including a plurality of flexible feeding portions having free extremities and variable speed mechanism including manually adjustable friction mechanism and operatively connected to said motor and whereby with the motor in each case rotating in the same direction either of said portions may be drawn in at any of a plurality of speeds including a predetermined cutting speed, a predetermined higher speed, or at fractional speeds determined by the adjustment of said friction mechanism.

138. A mining machine slidable on a mine bottom comprising a motor, cutting mechanism operatively connected thereto and including a cutter bar, and flexible feeding mechanism for feeding said bar longitudinally into a face and laterally along the same including a plurality of flexible feeding portions having free extremities and variable speed mechanism including fast and slow feed gearing and manually adjustable friction mechanism and operatively connected to said motor whereby with the motor in each case rotating in the same direction either of said portions may be drawn in at either fast or slow speed or at fractions of either speed determined by the adjustment of said friction mechanism.

139. A mining machine slidable on a mine bottom comprising a motor, cutting mechanism operatively connected thereto and including a cutter bar, and flexible feeding mechanism for feeding said bar longitudinally into and laterally along a face including a plurality of flexible feeding portions having free extremities and operative connections for drawing in one of said portions by power at a predetermined cutting speed while the other lengthens including variable speed mechanism and manually adjustable friction mechanism whereby with the motor rotating in the same direction as before said other portion may be drawn in at a plurality of speeds including a predetermined cutting speed.

140. A mining machine slidable on a mine bottom comprising a motor, cutting mechanism operatively connected thereto and including a cutter bar, and flexible feeding mechanism for feeding said bar longitudinally into and laterally along a face including a plurality of flexible feeding portions having free extremities and operative connections for drawing in one of said portions by power at a predetermined cutting speed while the other lengthens including variable speed mechanism and manually adjustable friction mechanism whereby with the motor rotating in the same direction as before said other portion may be drawn in at a plurality of speeds including a predetermined cutting speed and a predetermined higher speed.

141. A mining machine slidable on a mine bottom comprising a motor, cutting mechanism operatively connected thereto and including a cutter bar, and flexible feeding mechanism for feeding said bar longitudinally into and laterally along a face including a plurality of flexible feeding portions having free extremities and operative connections for drawing in one of said portions by power at a predetermined cutting speed while the other lengthens including variable speed mechanism and manually adjustable friction mechanism whereby with the motor rotating in the same direction as before said other portion may be drawn in at a plurality of speeds including a predetermined cutting speed or at a fractional speed determined by the adjustment of said friction device. 65
142. A mining machine slidable on a mine bottom comprising a motor, cutting mechanism operatively connected thereto and including a cutter bar, and flexible feeding mechanism for feeding said bar longitudinally into and laterally along a face including a plurality of flexible feeding portions having free extremities and operative connections for drawing in one of said portions by power at a predetermined cutting speed while the other lengthens including variable speed mechanism and manually adjustable friction mechanism whereby with the motor rotating in the same direction as before the other portion may be drawn in at a predetermined cutting speed, a predetermined higher speed, or at fractional speeds determined by the adjustment of said friction device. 70
143. A mining machine slidable on a mine bottom comprising a motor, cutting mechanism operatively connected thereto and including a cutter bar, and flexible feeding mechanism for feeding said bar longitudinally into and laterally along a face including a plurality of flexible feeding portions having free extremities and operative connections for drawing in one of said portions by power at a predetermined cutting speed while the other lengthens including fast and slow feed gearing and manually adjustable friction mechanism whereby with the motor rotating in the same direction as before said other portion may be drawn in at either fast or slow speed or at fractions of either speed determined by the adjustment of said friction mechanism. 75
144. A mining machine slidable on a mine bottom comprising a motor, cutting mechanism operatively connected thereto and including a cutter bar, and flexible feeding mechanism for feeding said bar longitudinally into and laterally along a face including a plurality of flexible feeding portions having free extremities and op- 80
- erative connections for drawing in one of said portions by power at a predetermined cutting speed while the other lengthens including fast and slow feed gearing and manually adjustable friction controlled mechanism whereby with the motor rotating in the same direction as before said other portion may be drawn in at either fast or slow speed, said connections also having provision for preventing simultaneous connection of both feeds. 85
145. A mining machine slidable on a mine bottom comprising a motor, cutting mechanism operatively connected thereto and including a cutter bar, and flexible feeding mechanism for feeding said bar longitudinally into and laterally along a face including a plurality of flexible feeding portions having free extremities and operative connections for drawing in one of said portions by power at a predetermined cutting speed while the other lengthens including fast and slow feed gearing and manually adjustable friction controlled mechanism whereby with the motor rotating in the same direction as before said other portion may be drawn in at either fast or slow feed, said connections also having interlocking connections whereby a change from one speed to another is inhibited without previously releasing the friction mechanism. 90
146. A mining machine slidable on a mine bottom comprising a motor, cutting mechanism including a cutter bar, and flexible feeding mechanism operative to effect machine movement during sumping and cutting and including advance and receding flexible feeding portions having free extremities and operative connections for drawing in with said motor in each case rotating in the same direction either of said portions while the other lengthens including connections for said receding portion comprising variable speed mechanism driven by said motor and manually adjustable friction mechanism whereby said portion may be drawn in at a plurality of speeds including a predetermined cutting speed. 100
147. A mining machine slidable on a mine bottom comprising a motor, cutting mechanism including a cutter bar, and flexible feeding mechanism operative to effect machine movement during sumping and cutting and including advance and receding flexible feeding portions having free extremities and operative connections for drawing in with said motor in each case rotating in the same direction either of said portions while the other lengthens including connections for said receding portion comprising variable speed mechanism driven by said motor and manually adjustable friction mechanism whereby said portion may be drawn in at a plurality of predetermined cutting speeds. 105
148. A mining machine slidable on a mine bottom comprising a motor, cutting mechanism including a cutter bar, and flexible feeding mechanism operative to effect machine movement during sumping and cutting and including advance and receding flexible feeding portions having free extremities and operative connections for drawing in with said motor in each case rotating in the same direction either of said portions while the other lengthens including connections for said receding portion comprising variable speed mechanism driven by said motor and manually adjustable friction mechanism whereby said portion may be drawn in at a plurality of predetermined cutting speeds. 110
149. A mining machine slidable on a mine bottom comprising a motor, cutting mechanism including a cutter bar, and flexible feeding mechanism operative to effect machine movement during sumping and cutting and including advance and receding flexible feeding portions having free extremities and operative connections for drawing in with said motor in each case rotating in the same direction either of said portions while the other lengthens including connections for said receding portion comprising variable speed mechanism driven by said motor and manually adjustable friction mechanism whereby said portion may be drawn in at a plurality of predetermined cutting speeds. 115
150. A mining machine slidable on a mine bottom comprising a motor, cutting mechanism including a cutter bar, and flexible feeding mechanism operative to effect machine movement during sumping and cutting and including advance and receding flexible feeding portions having free extremities and operative connections for drawing in with said motor in each case rotating in the same direction either of said portions while the other lengthens including connections for said receding portion comprising variable speed mechanism driven by said motor and manually adjustable friction mechanism whereby said portion may be drawn in at a plurality of predetermined cutting speeds. 120
151. A mining machine slidable on a mine bottom comprising a motor, cutting mechanism including a cutter bar, and flexible feeding mechanism operative to effect machine movement during sumping and cutting and including advance and receding flexible feeding portions having free extremities and operative connections for drawing in with said motor in each case rotating in the same direction either of said portions while the other lengthens including connections for said receding portion comprising variable speed mechanism driven by said motor and manually adjustable friction mechanism whereby said portion may be drawn in at a plurality of predetermined cutting speeds. 125

speeds including a cutting speed or at fractional speeds determined by the position of said friction mechanism.

148. A mining machine slidable on a mine bottom comprising a motor, cutting mechanism including a cutter bar, and flexible feeding mechanism operative to effect machine movement during sumping and cutting and including advance and receding flexible feeding portions having free extremities and operative connections for drawing in, with said motor in each case rotating in the same direction either of said portions while the other lengthens including connections for either of said portions comprising variable speed mechanism driven by said motor and manually adjustable friction mechanism whereby either of said portions may be drawn in at a plurality of speeds including a predetermined cutting speed.

149. A mining machine slidable on a mine bottom comprising a motor, cutting mechanism including a cutter bar, and flexible feeding mechanism operative to effect machine movement during sumping and cutting and including advance and receding flexible feeding portions having free extremities and operative connections for drawing in, with said motor in each case rotating in the same direction either of said portions while the other lengthens including connections for either of said portions comprising variable speed mechanism driven by said motor and manually adjustable friction mechanism whereby either of said portions may be drawn in at a plurality of predetermined speeds including a cutting speed or at fractional speeds determined by the position of said friction mechanism.

150. A mining machine slidable on a mine bottom comprising a motor, cutting mechanism reversibly operable by said motor and including a cutter bar, and flexible feeding mechanism for feeding said bar into a face and laterally along the face in either direction including a plurality of flexible feeding portions having free extremities and provision whereby either portion may function as a sumping portion and thereafter as a receding portion while its fellow functions as an advance portion, said mechanism also including operative connections whereby said machine may be sumped at a predetermined cutting speed along either first mentioned portion and then moved transversely along the face and the other portion at a predetermined cutting speed without reversing the cutting mechanism and while said first mentioned portion lengthens.

151. A mining machine slidable on a mine bottom comprising a motor, cutting mechanism reversibly operable by said motor and including a cutter bar, and flexible feeding mechanism for feeding said bar into a face

and laterally along the face in either direction including a plurality of flexible feeding portions having free extremities and provision whereby with single reverse anchoring operations of said extremities either portion may function as a sumping portion and thereafter as a receding portion while its fellow functions as an advance portion, said mechanism also including operative connections whereby said machine may be sumped at a predetermined cutting speed along either first mentioned portion and then moved transversely along the face and the other portion at a predetermined cutting speed without reversing the cutting mechanism and while said first mentioned portion lengthens.

152. A mining machine slidable on a mine bottom comprising a motor, cutting mechanism adapted to be reversibly driven thereby including a cutter chain carrying cutter bar, and flexible feeding mechanism for feeding said bar bodily laterally in either direction relative to a face including a plurality of flexible feeding portions having free extremities extendable during lateral cutting in one direction in advance and receding portions from longitudinally separated points in rear of the front end of said bar and having provision whereby during lateral cutting in the opposite direction said portions may be reversely disposed as receding and advance portions, said feeding mechanism also having operative connections whereby in either direction of rotation of said cutting mechanism the portion forming the receding portion may be drawn in at any of a plurality of speeds including a predetermined cutting speed and, without reversing the cutting mechanism, the portion forming the advance portion may thereafter be drawn in at a predetermined cutting speed while said receding portion lengthens.

153. A mining machine slidable on a mine bottom comprising a motor, cutting mechanism adapted to be driven thereby including a cutter chain carrying cutter bar, and flexible feeding mechanism for feeding said bar bodily laterally in either direction relative to a face including a plurality of flexible feeding portions having free extremities extendable during lateral cutting in one direction in advance and receding portions from longitudinally separated points in rear of the front end of said bar and having provision whereby during lateral cutting in the opposite direction said portions may be reversely disposed as receding and advance portions, said feeding mechanism also having operative connections whereby in either direction of rotation of said cutting mechanism the portion forming the receding portion may be drawn in at any of a plurality of speeds including a predetermined cutting

speed and a predetermined higher speed and without reversing the cutting mechanism the portion forming the advance portion may be drawn in at a predetermined cutting speed 5 while said receding portion lengthens.

154. A longwall mining machine slidable on a mine bottom comprising a motor, cutting mechanism driven thereby and disposed at one end of said machine including a pivotally connected cutter bar disposable longitudinally or laterally relative to said machine, and flexible feeding and guiding means including feed operating mechanism at the opposite end of said machine and a 10 plurality of flexible feeding portions each having one extremity connected to said feed operating mechanism and a free extremity, said means having provision for so disposing and drawing in one of said portions 15 as to move said bar at a cutting speed into a laterally disposed position beneath a face and, while said bar is so located and the other portion remains operatively connected at one end to said feed operating mechanism, so disposing and drawing in said other portion as to move said bar bodily laterally along the face at a cutting speed without reversing the direction of said cutting mechanism.

155. A longwall mining machine slidable on a mine bottom comprising a motor, cutting mechanism driven thereby and disposed at one end of said machine including a pivotally connected cutter bar disposable longitudinally or laterally relative to said machine, and flexible feeding and guiding means including feed operating mechanism at the opposite end of said machine and a plurality of flexible feeding portions each 20 having one extremity connected to said feed operating mechanism and a free extremity, said means having provision for so disposing and drawing in one of said portions as to move said bar at a cutting speed into a laterally disposed position beneath a face at either side of the machine and, while said bar is so located and said portions remain operatively connected at one end to said feed operating mechanism, so disposing and drawing in said other portion as to move said bar bodily laterally along the face at a cutting speed without reversing the direction of said cutting mechanism.

156. A longwall mining machine slidable on a mine bottom comprising a motor, cutting mechanism driven thereby and disposed at one end of said machine including a pivotally connected cutter bar disposable longitudinally or laterally relative to said machine, and flexible feeding and guiding means including a plurality of flexible feeding portions each having a free extremity and feed operating mechanism at the opposite end of the machine from the cutting 25 mechanism to which one extremity of each

of said portions is connected, said feed operating mechanism having provision for drawing in one portion at a cutting speed and the other at a higher speed, and said means having provision for so disposing and drawing in one of said portions as to move said bar at a cutting speed into a laterally disposed position beneath a face and, while said bar is so located and the other portion remains operatively connected at one end to said operating mechanism, so disposing and drawing in said other portion as to move said bar bodily laterally along the face at a cutting speed without reversing the direction of said cutting mechanism. 70

157. A longwall mining machine slidable on a mine bottom comprising a motor, having a rotor whose axis of rotation is parallel to the major dimension of the machine, cutting mechanism driven thereby and disposed at one end of said machine including a pivotally connected cutter bar disposable longitudinally or laterally relative to said machine, and flexible feeding and guiding means including feed operating mechanism including winding means rotatable on a vertical axis at the opposite end of said machine and a plurality of flexible feeding portions each having one extremity connected to said feed operating mechanism and a free extremity, said means having provision for so disposing and drawing in one of said portions at a cutting speed as to move said bar into a laterally disposed position beneath a face and, while said bar is so located and the other portion remains operatively connected at one end to said feed operating mechanism, so disposing and drawing in said other portion at a cutting speed as to move said bar bodily laterally along the face without reversing the direction of the cutting mechanism, said feeding and guiding means also including means for drawing in said last mentioned portion at a higher speed with the motor rotating in the same direction as during the drawing in at said cutting speed. 85

158. A longwall mining machine slidable on a mine bottom comprising a motor, cutting mechanism driven thereby and disposed at one end of said machine including a pivotally connected cutter bar disposable longitudinally or laterally relative to said machine, and flexible feeding and guiding means for moving said bar into a laterally extending position beneath a face and thereafter moving said bar bodily laterally along a face including feed operating mechanism at the opposite end of said machine and a plurality of flexible feeding portions each having one extremity connected to said feed operating mechanism and a free extremity, said means having provision for drawing in one of said portions at a fast speed or at a slow speed with the motor running in each 100 105 110 115 120 125 130

case in the same direction and without reversing the direction of said cutting mechanism drawing in the other portion at either a fast or slow speed.

- 6 159. A longwall mining machine slidable on a mine bottom comprising a motor, cutting mechanism driven thereby and disposed at one end of said machine including a pivotally connected cutter bar disposable longitudinally or laterally relative to said machine, and flexible feeding and guiding means for moving said bar into a laterally extending position beneath a face and thereafter moving said bar bodily laterally along 10 a face including feed operating mechanism at the opposite end of said machine and a flexible feeding portion, said means having provision whereby said flexible feeding portion may be drawn in by power at fast or 15 slow speed or paid out by power at fast or slow speed, all with the motor running in one direction and without reversing said cutting mechanism.

160. A mining machine slidable on a mine bottom comprising a motor, cutting mechanism driven thereby including a cutter carrying cutter bar, and feeding and guiding mechanism for summing said bar longitudinally into and thereafter feeding 25 it laterally along a face with said cutting mechanism rotating in the same direction as during the summing operation including a plurality of flexible feeding portions each having a free extremity, guiding means 30 therefor, and winding means therefor driven by said motor, said winding means being connectible selectively to said motor without reversal of the latter to draw in each portion at a predetermined cutting speed or 35 at a predetermined higher speed, in excess of the maximum potential cutting speed of said machine under normal working conditions, the change from drawing in at the cutting speed to the drawing in at the higher speed involving only changes in the operative connections between said motor and winding means.

161. A mining machine slidable on a mine bottom comprising a motor, cutting mechanism driven thereby including a cutter carrying cutter bar, and feeding and guiding mechanism for summing said bar longitudinally into and thereafter feeding it laterally along a face with said cutting mechanism rotating in the same direction as during the summing operation including a plurality of flexible feeding portions each having a free extremity, guiding means therefor, and winding means therefor driven by said motor, said winding means including mechanism driven by said motor without reversal of the latter for drawing in one portion at a predetermined cutting speed or a predetermined higher speed and mechanism

for drawing in the other portion at the same speeds.

162. A mining machine slidable on a mine bottom comprising a motor, cutting mechanism driven thereby including a cutter carrying cutter bar, and feeding and guiding mechanism for summing said bar generally longitudinally into and thereafter feeding it laterally along a face with said cutting mechanism rotating in the same direction as during the summing operation including a plurality of flexible feeding portions each having a free extremity, guiding means therefor, and winding means therefor driven by said motor, said winding means including a fast feed gear train and a slow feed gear train, means for drawing in either of said portions through said slow feed gear train without reversing the motor, and means for drawing in one of the same through said fast feed gear train.

163. A mining machine slidable on a mine bottom comprising a motor, cutting mechanism driven thereby including a cutter carrying cutter bar, and feeding and guiding mechanism for summing said bar generally longitudinally into and thereafter feeding it laterally along a face with said cutting mechanism rotating in the same direction as during the summing operation including a plurality of flexible feeding portions each having a free extremity, guiding means therefor, and winding means therefor driven by said motor, said winding means including a fast feed gear train and a slow feed gear train adapted to be driven by said motor, and means for drawing in either portion through either train without reversing said motor or changing the mode of connection of either portion to said winding means.

164. A mining machine slidable on a mine bottom comprising a motor, cutting mechanism driven thereby including a cutter carrying cutter bar, and feeding and guiding mechanism for summing said bar longitudinally into and thereafter feeding it laterally along a face with said cutting mechanism rotating in the same direction as during the summing operation including a plurality of flexible feeding portions each having a free extremity, guiding means therefor, and winding means therefor driven by said motor, said winding means including a fast feed gear train and a slow feed gear train driven by said motor, automatically releasable friction mechanism in either train, means for drawing in either portion through said slow feed gear train without reversing the motor, and means for drawing in one of the same through said fast feed gear train.

165. A mining machine slidable on a mine bottom comprising a motor, cutting mechanism driven thereby including a cutter carrying cutter bar, and feeding and guiding

- mechanism for summing said bar longitudinally into and thereafter feeding it laterally along a face with said cutting mechanism rotating in the same direction as during the summing operation including a plurality of flexible feeding portions each having a free extremity, guiding means therefor, and winding means therefor driven by said motor, said winding means including a fast feed gear train and a slow feed gear train driven by said motor, automatically releasable friction mechanism in either train, and means for drawing in either portion through either train without reversing said motor or changing the mode of connection of either portion to said winding means.

166. A mining machine slidable on a mine bottom comprising a motor, cutting mechanism driven thereby including a cutter carrying cutter bar, and feeding and guiding mechanism for summing said bar into and thereafter feeding it laterally along a face with said cutting mechanisms rotating in the same direction as during the summing operation including a plurality of flexible feeding portions each having a free extremity, guiding means therefor, and winding means therefor driven by said motor, said winding means including a fast feed gear train and a slow feed gear train driven by said motor, and means for drawing in either portion through either train without reversing said motor including friction mechanism controlling each feed and freely releasable manually to reduce either geared feed.

167. A mining machine slidable on a mine bottom comprising a motor, cutting mechanism driven thereby including a cutter carrying cutter bar, and feeding and guiding mechanism for summing said bar into and thereafter feeding it laterally along a face with said cutting mechanism rotating in the same direction as during the summing operation including a plurality of flexible feeding portions each having a free extremity, guiding means therefor, and winding means therefor driven by said motor, said winding means including a fast feed gear train and a slow feed gear train driven by said motor and means for drawing in either portion through either train without reversing said motor including a single manually adjustable friction mechanism controlling all feeds.

168. A mining machine slidable on a mine bottom comprising a motor, cutting mechanism driven thereby including a cutter carrying cutter bar, and feeding and guiding mechanism for summing said bar longitudinally into and feeding it laterally relative to a face with said cutting mechanism rotating in the same direction as during the summing operation including a plurality of flexible feeding portions each having a free extremity, guiding means therefor, and winding means therefor driven by said motor, said winding means being connectible selectively to said motor without reversal of the latter to draw in each portion at a predetermined cutting speed or at a predetermined higher speed substantially in excess of the maximum potential cutting speed of said machine under normal working conditions, or to draw in one portion at a predetermined cutting speed while permitting lengthening of the other, all without change in the mode of connection of said winding means to said portions.

169. A mining machine slidable on a mine bottom comprising a motor, cutting mechanism driven thereby including a cutter carrying cutter bar, and feeding and guiding mechanism for summing said bar into and feeding it laterally relative to a face with said cutting mechanism rotating in the same direction as during the summing operation including a plurality of flexible feeding portions each having a free extremity, guiding means therefor, and winding means therefor driven by said motor, said winding means being connectible relatively to said motor without reversal of the latter to draw in either portion at a predetermined cutting speed or at a predetermined higher speed or to draw in either portion at a predetermined cutting speed while permitting lengthening of the other.

170. A mining machine slidable on a mine bottom comprising a motor, cutting mechanism driven thereby including a cutter carrying cutter bar, and feeding and guiding mechanism for summing said bar longitudinally into and thereafter feeding it laterally along a face with said cutting mechanism rotating in the same direction as during the summing operation including flexible feeding portions disposable from the opposite sides of said machine, each having a free extremity, guiding means therefor, and winding means therefor driven by said motor, said winding means being connectible selectively to said motor without reversal of the latter to draw in one of said portions at a predetermined cutting speed or at a predetermined higher speed substantially in excess of the maximum potential cutting speed of said machine under normal working conditions or to draw in the other portion at a predetermined cutting speed while permitting lengthening of the first mentioned portion.

171. A mining machine slidable on a mine bottom comprising a motor, cutting mechanism driven thereby including a cutter carrying cutter bar, and feeding and guiding mechanism for summing said bar into and thereafter feeding it laterally along a face with said cutting mechanism rotating in the same direction as during the summing

- operation including a plurality of flexible feeding portions adapted to provide a summing member operatively disposable substantially longitudinally of the rib side of the machine and adapted thereafter to effect lateral cutting, guiding means therefor, and winding means for said portions driven by said motor, said winding means including a fast geared feed, a slow geared feed, means for drawing in each portion through either feed without reversal of said motor, and friction mechanism for each feed automatically releasable on overload.
172. A mining machine slideable on a mine bottom comprising a motor, cutting mechanism driven thereby including a cutter carrying cutter bar, and feeding and guiding mechanism for summing said bar into and thereafter feeding it laterally along a face with said cutting mechanism rotating in the same direction as during the summing operation including a plurality of flexible feeding portions adapted to provide a summing member disposable substantially longitudinally of the rib side of the machine and adapted thereafter to effect lateral cutting, and winding means for said portions, said winding means including a fast geared feed, a slow geared feed, means for drawing in either portion through either feed without reversal of said motor, and friction mechanism for each feed automatically releasable on overload and manually adjustable to reduce the speed of any geared feed.
173. The combination with a mining machine comprising cutting mechanism including a motor and a cutter carrying cutter bar, of flexible feeding means for feeding said bar into and laterally relative to a face including a plurality of flexible feeding portions each having a free extremity, guiding means therefor, and feed operating means operative to effect summing or lateral feeding relative to said flexible feeding means including fast and slow feed gearing selectively driven by said motor, winding means, operative connections therefor at will driven by said slow gearing to draw in either portion at a slow speed without reversing said motor or driven by said fast gearing to draw in one portion at a fast speed without reversing said motor, and frictional mechanism between said motor and said winding means controlling all of said feeds.
174. The combination with a mining machine comprising cutting mechanism including a motor and a cutter carrying cutter bar, of flexible feeding means for feeding said bar into and laterally relative to a face including a plurality of flexible feeding portions each having a free extremity, guiding means therefor, and feed operating means operative to effect summing or lateral feeding relative to said flexible feeding means including fast and slow feed gearing selectively driven by said slow gearing to draw in either portion at a slow speed without reversing said motor or driven by said fast gearing to draw in one portion at a fast speed without reversing said motor, and frictional mechanism between said motor and said winding means controlling all of said feeds.
175. The combination with a mining machine comprising cutting mechanism including a motor and a cutter carrying cutter bar, of flexible feeding and guiding means for feeding said bar into and laterally relative to a face including a plurality of flexible feeding portions each having a free extremity, guiding means therefor, and feed operating means operative to effect summing or lateral feeding relative to said flexible feeding means including fast and slow gear- 75 80 85 90 95 100 105 110 115 120 125 130
176. The combination with a mining machine comprising cutting mechanism including a motor and a cutter carrying cutter bar, of flexible feeding and guiding means for feeding said bar generally longitudinally into and laterally relative to a face including a plurality of flexible feeding portions each having a free extremity, guiding means therefor, and feed operating means operative to effect summing or lateral feeding relative to said flexible means including fast and slow gearing selectively driven by said motor without reversal thereof, winding means, operative connections therefor driven at will by said slow gearing to draw in either portion at a slow speed without reversing said motor or driven by said fast gearing to draw in one portion at a fast speed, and frictional mechanism between said motor and said winding means operative under a normal load when either portion is drawn in and manually adjustable at will to reduce the geared speeds.
177. The combination with a mining machine comprising cutting mechanism including a motor and a cutter carrying cutter bar, of flexible feeding and guiding means for feeding said bar generally longitudinally into and laterally relative to a face including a plurality of flexible feeding portions each having a free extremity, guiding means therefor, and feed operating means operative to effect summing and lateral feeding relative to said flexible means including fast and slow gearing selectively driven by said

motor, winding means, operative connections therefor driven at will by either said fast or said slow gearing to draw in either portion at a fast or a slow speed without reversing said motor, and manually adjustable mechanism between said motor and said winding mechanism freely adjustable to vary the geared speeds, the operations necessary to change from slow to fast speed drawing in involving solely changes in the operative connections between said winding mechanism and said motor.

178. The combination with a mining machine comprising cutting mechanism including a motor and a cutter carrying cutter bar, of flexible feeding and guiding means for feeding said bar into and laterally relative to a face including a plurality of flexible feeding portions each having a free extremity, guiding means therefor, and feed operating means operative to effect sumping and lateral feeding relative to said flexible feeding means including fast and slow gearing selectively driven by said motor, winding means, operative connections therefor driven at will by either said fast or said slow gearing to draw in either portion at a fast or a slow speed without reversing said motor, and mechanism between said motor and said winding mechanism adjustable to reduce the geared speeds and including a manually adjustable freely operable friction element.

179. A mining machine slidable relative to a mine bottom comprising a motor, cutting mechanism operatively connected thereto including a cutter carrying cutter bar, flexible feeding and guiding means for feeding said bar generally longitudinally into and laterally along a face including a plurality of flexible feeding portions each having a free extremity, guiding means therefor, winding means for said flexible means, and operative transmission connections between said winding means and said motor operative without reversal of the latter to effect sumping and lateral feeding and to draw in either portion at different speeds including a predetermined slow or cutting speed and a higher speed, said connections including slow speed gearing, manually controllable means automatically releasable on overload for obtaining feeds slower than the geared feed, and cooperating mechanism for selectively drawing in the desired portion at the geared speed.

180. A mining machine slidable relative to a mine bottom comprising a motor, cutting mechanism operatively connected thereto including a cutter carrying cutter bar, flexible feeding and guiding means for feeding the latter generally longitudinally into and laterally along a face including a plurality of flexible feeding portions each having a free extremity, guiding means therefor, winding means for said flexible means, and operative

transmission connections between said winding means and said motor operative without reversal of the latter to effect sumping and lateral feeding and to draw in either portion at different speeds including a predetermined slow or cutting speed and a higher speed, said connections including variable speed gearing common to the drawing in of both portions, and cooperating mechanism for selectively drawing in the desired portion at the desired geared speed.

181. A mining machine slidable relative to a mine bottom comprising a motor, cutting mechanism operatively connected thereto including a cutter carrying cutter bar, flexible feeding and guiding means for feeding the latter generally longitudinally into and laterally along a face including a plurality of flexible feeding portions each having a free extremity, guiding means therefor, winding means for said flexible means, and operative transmission connections between said winding means and said motor operative without reversal of the latter to effect sumping and lateral feeding and to draw in either portion at different speeds including a predetermined slow or cutting speed and at a higher speed, said connections including plural speed gearing common to the drawing in of both portions, frictional mechanism automatically releasable upon overload of any feed, and cooperating mechanism for selectively drawing in the desired portion at the desired geared speed.

183. A mining machine slidable relative to a mine bottom comprising a motor having a power shaft longitudinally disposed relative to said machine, cutting mechanism operatively connected to said motor including a cutter carrying cutter bar, flexible feeding and guiding means for feeding said bar generally longitudinally into and laterally along a face including a plurality of flexible feeding portions each having a free extremity, guiding means therefor, winding means for said flexible means disposed at the opposite side of the median transverse plane of said motor from the outer end of said cutter bar, and operative transmission means between said winding means and said motor for effecting sumping and lateral feeding operative to draw in either portion at a predetermined low or cutting speed without reversing said motor or to draw in one portion at a higher speed without reversing said motor, said means including plural speed gearing driven wholly from one end of said motor, adjustable connections for selecting the portion to be drawn in, and adjustable connections for selecting the speed.

183. A mining machine slidable relative to a mine bottom comprising a motor, cutting mechanism operatively connected there-

- to including a cutter carrying cutter bar, flexible feeding and guiding means for feeding said bar longitudinally into and laterally along a face including a plurality of flexible feeding portions each having a free extremity, guiding means therefor, winding means for said flexible means, and operative transmission means between said winding means and said motor for effecting sumping and lateral feeding operative to draw in either portion at a predetermined low or cutting speed without reversing said motor or to draw in one portion at a higher speed without reversing said motor, said means including plural speed gearing, adjustable connections for selecting the portion to be drawn in, adjustable connections for selecting the speed, and frictional means releasable on overload of any feed.
184. A mining machine slidably relative to a mine bottom comprising a motor, cutting mechanism operatively connected thereto including a cutter carrying cutter bar, flexible feeding and guiding means for feeding said bar longitudinally into and laterally along a face including a plurality of flexible feeding portions each having a free extremity, guiding means therefor, winding means for said flexible means, and operative transmission means between said winding means and said motor for effecting sumping and lateral cutting operative to draw in either portion at a predetermined slow or cutting speed without reversing said motor or to draw in one portion at a higher speed substantially in excess of the maximum potential cutting speed of the machine under normal working conditions without reversing said motor, said means including plural speed gearing, adjustable connections for selecting the portion to be drawn in, adjustable connections for selecting the speed, and frictional controlling means through which power is supplied to draw in either of said portions, said means being manually controllable to reduce the geared feeds at will.
185. A mining machine slidably relative to a mine bottom comprising a motor, cutting mechanism operatively connected thereto including a cutter carrying cutter bar, flexible feeding and guiding means for feeding said bar generally longitudinally into and laterally along a face including a plurality of flexible feeding portions each having a free extremity, guiding means therefor, winding means for said flexible means, and operative transmission means between said winding means and said motor for effecting sumping and lateral feeding operative without reversing said motor to draw in either portion at a predetermined slow or cutting speed or to draw in one portion at a higher speed, said means including plural speed gearing, adjustable connections for selecting the portion to be drawn in, adjustable controlling means for selecting the speed, and frictional means releasable on overload and manually controllable to reduce the geared feeds.
186. A mining machine slidably supported on a mine bottom comprising a motor, cutting mechanism operatively connected thereto and including a cutter carrying cutter bar, flexible feeding means comprising a plurality of flexible feeding portions each having a free extremity, guiding means therefor, winding means therefor, and operative transmission connections between said winding means and said motor and operative without reversal of the latter to draw in either portion at any of a plurality of predetermined speeds including a predetermined slow or cutting speed and a predetermined higher speed substantially in excess of the maximum potential cutting speed of said machine under normal working conditions.
187. A mining machine slidably supported on a mine bottom comprising a motor, cutting mechanism operatively connected thereto and including a cutter carrying cutter bar, flexible feeding means comprising a plurality of flexible feeding portions each having a free extremity, guiding means therefor, winding means therefor, and operative transmission connections between said winding means and said motor and operative without reversal of the latter to draw in either portion at any of a plurality of predetermined speeds including a predetermined slow or cutting speed and a predetermined higher speed substantially in excess of the maximum potential cutting speed of said machine under normal working conditions, said connections including plural speed gearing, and cooperating transmission mechanism for selectively drawing in the desired portion at the desired speed.
188. A mining machine slidably supported on a mine bottom comprising a motor, cutting mechanism operatively connected thereto and including a cutter carrying cutter bar, flexible feeding means comprising a plurality of flexible feeding portions each having a free extremity, guiding means therefor, winding means therefor, and operative transmission connections between said winding means and said motor for drawing in either portion at any of a plurality of predetermined speeds including a predetermined slow or cutting speed and a predetermined higher speed substantially in excess of the maximum potential cutting speed of said machine under normal working conditions, said connections including plural speed gearing, and cooperating manually controllable transmission mechanism for selectively drawing in the desired portion at the desired speed.

drawing in the desired portion at the desired speed including manually controllable means for obtaining feeds slower than the geared feeds.

189. A mining machine slidably supported on a mine bottom comprising a motor, cutting mechanism operatively connected thereto and including a cutter carrying cutter bar, flexible feeding means comprising a plurality of flexible feeding portions each having a free extremity, guiding means therefor, winding means therefor, and operative transmission connections between said winding means and said motor and operative without reversal of the latter to draw in either portion at any of a plurality of predetermined speeds including a predetermined slow or cutting speed, said connections including plural speed gearing, and cooperating mechanism for selectively drawing in the desired portion at the desired speed including a single manually controllable frictional means for obtaining feeds slower than the geared feeds and included in the transmission connections during the drawing in of each portion.

190. A mining machine slidably supported on a mine bottom comprising a motor, cutting mechanism operatively connected thereto and including a cutter carrying cutter bar, flexible feeding means comprising a plurality of flexible feeding portions each having a free extremity, guiding means therefor, winding means therefor, and operative transmission connections between said winding means and said motor operative without reversal of the latter to draw in either portion at any of a plurality of predetermined speeds including a predetermined slow or cutting speed and a predetermined higher speed in excess of the maximum potential cutting speed of the machine under normal working conditions, said connections including variable speed gearing through which power may be transmitted for the drawing in of each portion, mechanism for selecting the portion to be drawn in, and transmission controlling mechanism for selecting the predetermined speed at which it is to be drawn in.

191. A mining machine slidably supported on a mine bottom comprising a motor, cutting mechanism operatively connected thereto and including a cutter carrying cutter bar, flexible feeding means comprising a plurality of flexible feeding portions each having a free extremity, guiding means therefor, winding means therefor, and operative transmission connections between said winding means and said motor operative without reversal of the latter to draw in either portion at any of a plurality of predetermined speeds including a predetermined slow or cutting speed, said connections including plural speed gearing, mecha-

nism for selecting the portion to be drawn in, transmission controlling mechanism for selecting the predetermined speed at which it is to be drawn in, and yielding mechanism for said feeds automatically releasable on overload.

192. A mining machine slidably supported on a mine bottom comprising a motor, cutting mechanism operatively connected thereto and including a cutter carrying cutter bar, flexible feeding means comprising a plurality of flexible feeding portions each having a free extremity, guiding means therefor, winding means therefor, and operative transmission connections between said winding means and said motor operative without reversal of the latter to draw in either portion at any of the same plurality of predetermined speeds including a predetermined slow or cutting speed, said connections including variable speed gearing, mechanism for selecting the portion to be drawn in, transmission controlling mechanism for selecting the predetermined speed at which it is to be drawn in, and mechanism through which power is supplied to draw in either of said portions, said last mentioned mechanism being freely controllable manually to obtain feeds slower than the geared feeds.

193. A mining machine slideable relative to a mine bottom comprising a motor, cutting mechanism including a cutter bar operatively connected thereto, flexible feeding means comprising a plurality of flexible feeding portions each having a free extremity, guiding means therefor, winding means therefor, and operative transmission connections between said winding means and said motor operative without reversal of the latter to draw in either portion at any of a plurality of predetermined speeds including a predetermined slow or cutting speed, said connections including adjustable fast and slow speed gearing through which power is transmitted during the drawing in of each portion and a manually adjustable frictional controlling element.

194. A mining machine slideable relative to a mine bottom comprising a motor, cutting mechanism including a cutter bar operatively connected thereto, flexible feeding means comprising a plurality of flexible feeding portions each having a free extremity, guiding means therefor, winding means therefor, said flexible portions being adapted to cooperate with stationary anchor means to effect sumping and moving of said machine across a face, and operative transmission connections between said winding means and said motor operative without reversal of the latter to draw in either portion at any of a plurality of speeds including a predetermined slow or cutting speed, said connections including adjustable fast and

- slow speed gearing, and adjustable connections for enabling either flexible portion to be drawn in through either gearing including a supplemental variable speed device 5 through which power is transmitted in drawing in either of said portions.
195. A mining machine slidably supported on a mine bottom comprising a motor, cutting mechanism operatively connected thereto and including a cutter carrying cutter bar, flexible feeding means comprising a plurality of flexible feeding portions each having a free extremity, guiding means therefor, winding means therefor, and operative 10 transmission connections between said winding means and said motor operative without reversal of the latter to draw in either portion at any of the same plurality of predetermined speeds including a predetermined 15 slow or cutting speed, said connections including variable speed gearing, mechanism for selecting the portion to be drawn in, mechanism for selectively connecting it to said gearing to obtain the predetermined 20 speed at which it is to be drawn in, and supplemental adjustable variable speed mechanism for varying the predetermined speed selected.
196. A mining machine slidably supported on a mine bottom comprising a motor, cutting mechanism operatively connected thereto and including a cutter carrying cutter bar, flexible feeding means comprising a plurality of flexible feeding portions each 25 having a free extremity, guiding means therefor, winding means therefor, and operative transmission connections between said winding means and said motor operative without reversal of the latter to draw in either portion at any of a plurality of predetermined speeds including a predetermined slow or cutting speed, said connections including a plurality of transmission trains, one operative to deliver power at a predetermined slow or cutting speed and the other operative to deliver power at a predetermined higher speed, and connections whereby each train may draw in each flexible feeding portion, and supplemental manually controllable mechanism whereby feeds slower than the geared speeds may be obtained.
197. A mining machine slidably supported on a mine bottom comprising a motor, cutting mechanism operatively connected thereto and including a cutter carrying cutter bar adapted to be sumped longitudinally into the coal and operative on opposite lateral presentation to the coal with the cutter oppositely actuated to cut and clear kerfs in opposite directions, flexible feeding means 50 comprising a plurality of flexible feeding portions each having a free extremity, winding means therefor, guiding means therefor, and operative transmission connections between said winding means and said motor operative without reversal of the latter or

change in the mode of operative connection of said portions to said winding means to draw in either portion at any of a plurality of predetermined speeds including a predetermined slow or cutting speed, said connections including a plurality of transmission trains, one operative to deliver power at a predetermined slow or cutting speed and the other operative to deliver power at a predetermined higher speed, and connections whereby each train may draw in each flexible feeding portion.

198. A mining machine slidably supported on a mine bottom comprising a motor, cutting mechanism operatively connected thereto and including a cutter carrying cutter bar, flexible feeding means comprising a plurality of flexible feeding portions each having a free extremity, guiding means therefor, winding means therefor, and operative transmission connections between said winding means and said motor operative without reversal of said motor to draw in either portion at any of a plurality of predetermined speeds including a predetermined slow or cutting speed, said connections including a plurality of transmission trains, one operative to deliver power at a predetermined slow or cutting speed and the other operative to deliver power at a predetermined higher speed, and connections whereby each train may draw in each flexible feeding portion.

199. A mining machine slidably supported on a mine bottom comprising a motor, cutting mechanism operatively connected thereto and including a cutter carrying cutter bar, flexible feeding means comprising a plurality of flexible feeding portions each having a free extremity, guiding means therefor, winding means therefor, and operative transmission connections between said winding means and said motor operative without reversal of the latter to draw in either portion at any of a plurality of predetermined speeds including a predetermined slow or cutting speed, said connections including a plurality of transmission trains, one operative to deliver power at a predetermined slow or cutting speed and the other operative to deliver power at a predetermined higher speed, and connections whereby each train may draw in each flexible feeding portion, and supplemental manually controllable mechanism whereby feeds slower than the geared speeds may be obtained.

200. A mining machine slidably on a mine bottom comprising a motor, cutter mechanism driven thereby including a cutter carrying cutter bar, and feeding and guiding mech-

anism for sumping said bar generally longitudinally into and thereafter feeding it laterally along a face with said cutting mechanism rotating in the same direction as during the sumping operation, said mechanism including a plurality of flexible feeding portions each having a free extremity, guiding means, and winding means driven by said motor, said winding means comprising a single fast feed gear train and a single slow feed gear train adapted to be driven by said motor, and means for drawing in either portion through either train without reversing said motor.

201. A mining machine slideable on a mine bottom comprising a motor, cutting mechanism driven thereby including a cutter carrying cutter bar, and feeding and guiding mechanism for sumping said bar generally longitudinally into and thereafter feeding it laterally along a face with said cutting mechanism rotating in the same direction as during the sumping operation, said mechanism including a plurality of flexible feeding portions each having a free extremity, guiding means, and winding means driven by said motor, said winding means comprising a single fast feed gear train and a single slow feed gear train adapted to be driven by said motor, and means for drawing in one of said portions through either of said trains or the other portion through one of said trains without reversing said motor.

202. In a mining machine, a machine frame slideable on a mine bottom during cutting, feeding means on said machine frame adapted to cooperate with a plurality of flexible feeding portions having free extremities in feeding and guiding said frame, and actuating mechanism for said feeding means whereby either portion may be drawn in including a motor, transmission connections driven thereby for driving said feeding means at a plurality of predetermined speeds including a predetermined cutting speed and in either direction, means to adjust said transmission connections to simultaneously control the direction of feed and the feeding speed, and additional means for controlling the direction of feed.

203. The combination with a mining ma-

chine having projecting cutting mechanism and slideable on a mine bottom, of flexible feeding mechanism including a plurality of flexible feeding portions each having a free extremity, a driving motor therefor operatively connected to said cutting mechanism, and operative connections more remote from said projecting cutting mechanism than the end of said motor adjacent the outer end of said projecting cutting mechanism whereby different portions may be drawn in at a predetermined slow or cutting speed or at a predetermined faster speed substantially in excess of the maximum potential cutting speed of said machine during normal working conditions while said motor rotates in the same direction including a plurality of clutches.

204. The combination with a mining machine having projecting cutting mechanism and slideable on a mine bottom, of flexible feeding mechanism including a plurality of flexible feeding portions each having a free extremity, a driving motor therefor operatively connected to said cutting mechanism, and operative connections whereby different portions may be drawn in at a predetermined slow or cutting speed or at a predetermined faster speed while said motor rotates in the same direction including a plurality of clutches and controlling mechanism inhibiting simultaneous operation of said clutches.

205. In a mining machine, a machine frame slideable on its bottom directly on a mine bottom, cutting mechanism projecting therefrom, and feeding mechanism on said frame more remote from said cutting mechanism than the end of said motor adjacent the outer extremity of said cutting mechanism and including a plurality of flexible feeding portions and mechanism for drawing in either portion at different speeds including a predetermined cutting speed comprising multi-speed driving mechanism, independent mechanical reversing mechanism, and independently operable controlling mechanism for said multi-speed driving and reversing mechanisms.

In testimony whereof I affix my signature.

MORRIS P. HOLMES.
